ABSTRACT

A machine for making spacer-expanders for piston oil rings of the type described in U.S. Pat. No. 3,477,732. The machine comprises a punch press having a plurality of stations through which strip stock is fed progressively in accurately predetermined increments, the strip stock being worked between dies at each station to transform the strip stock into completed rings. The press includes one or more punching stations where the strip stock is pierced and blanked, one or more forming stations where the pierced and notched strip is bent to form the spring legs of the spacer-expander and then curled into a channel-shaped cross-section, a coiling station where the channel-shaped stock is fashioned into a coil, and a cut-off station where each coil is sheared from the strip to form the semi-finished ring. The press also includes a special transfer apparatus for transferring the semi-finished ring to a final work station wherein the end joints are trimmed and formed to final configuration, after which the finished rings are loaded automatically in stacked relation on a cylindrical mandrel.

MACHINE FOR FORMING PISTON RING SPACER-EXPANDERS FROM STRIP STOCK

This application is a division of my copending application Ser. No. 39,498, filed May 21, 1970, now U.S. Pat. No. 3,646,797 and entitled "Machine for Forming Piston Ring Spacer-Expanders From Strip Stock."

This invention relates generally to a punch press and particularly to an apparatus for punching metal in the form of a strip and forming such punched strip into rings.

More specifically, the invention relates to an apparatus for progressively forming in a continuous operation a flat ribbon metal strip into spacer-expander spring rings of the type commonly located between thin metallic rails in the oil groove of a piston of an internal combustion engine.

An object of this invention is to enable production of such rings accurately, economically and at a high rate.

Another object is to provide an improved machine capable of automatically forming spacer-expanders of the type disclosed in U.S. Pat. No. 3,477,732, particularly in connection with FIGS. 1-5 inclusive and FIGS. 15 and 16 thereof.

A further object is to provide an improved machine capable of performing the improved method of making such a spacer-expander as disclosed in a co-pending application of Frank G. Warrick, Ser. No. 448,059, filed Apr. 14, 1965, now U.S. Pat. No. 3,477,732 entitled "Method of Forming a Spacer-Expander," and assigned to the assignee of the present application.

A further object is to provide an improved machine of the above character utilizing certain components and functions of the machine disclosed and claimed in U.S. Pat. No. 2,925,847, assigned to the assignee of the present application, and to improve upon said prior machine.

Other objects, features and advantages of the apparatus of this invention will become apparent from the following detailed description and accompanying drawings wherein:

FIG. 1 is a fragmentary front elevational view of an exemplary but preferred embodiment of the machine of the present invention.

FIGS. 2, 3 and 4 are fragmentary plan views of the strip stock respectively showing the operations performed thereon at the first, second and third punching, blanking and bending stations of the machine.

FIG. 5 is a fragmentary perspective view of the strip stock illustrating the feet and leg bending operations performed thereon successively at stations Nos. 3 and 4 respectively.

FIG. 6 is a fragmentary view partially in vertical elevation and partially in vertical center section through the strip guide infeeding mechanism and leg bending dies of station No. 4.

FIGS. 7 and 8 are fragmentary end elevational and part vertical sectional views taken generally on the line 7-7 of FIG. 6 and respectively illustrating the dies of station No. 4 in their open and closed positions.

FIG. 9 is a fragmentary plan view of the strip infeed guide of station No. 4.

FIGS. 10 and 11 are fragmentary enlarged views of the dies as viewed in FIGS. 7 and 8 respectively.

FIG. 12 is a fragmentary front elevational view showing a portion of the die structure shown in FIG. 6 but enlarged thereover and with the dies in closed position.

FIG. 13 is a vertical sectional view taken on the line 13-13 of FIG. 5 but enlarged thereover.

FIG. 14 is a fragmentary front elevational view of the dies of station No. 5 shown partially in vertical center section and with the dies closed.

FIG. 15 is a fragmentary end elevational view of the entrance to station No. 5 taken on the line 15-15 of FIG. 14.

FIG. 16 is a fragmentary vertical sectional view taken on the line 16-16 of FIG. 21 and illustrating the progressive strut bending operation being simultaneously performed by the last even of the ten punches and associated dies of station No. 5.

FIGS. 17, 18, 19, 20 and 21 are fragmentary vertical sectional views taken respectively on the line 17-17 of FIG. 14 and lines 18-18, 19-19, 20-20 and 21-21 of FIG. 16.

FIG. 22 is a vertical sectional view taken on the line 22-22 of FIG. 16 illustrating the finished cross-sectional contour of the strip as it emerges from station No. 5.

FIG. 23 is a fragmentary horizontal sectional view taken on the line 23-23 of FIG. 14 illustrating the stationary stripper components in the lower die shoe of station No. 5.

FIG. 24 is a fragmentary horizontal plan view of a portion of the structure shown in FIG. 23 with the stationary stripper parts removed to better illustrate the underlying movable stripper and stationary forming dies in the lower die shoe.

FIGS. 25, 26 and 27 are fragmentary vertical sectional views taken respectively on the lines 25-25, 26-26 and 27-27 of FIG. 14.

FIG. 28 is a fragmentary perspective view of the left-hand stripper plate of station No. 5 shown by itself.

FIG. 29 is a fragmentary front elevational view of a portion of the induction heating coil of station No. 6 and also illustrating the coiling and cut-off apparatus of station No. 7 of the machine.

FIG. 30 is a fragmentary front elevational view of the components of station No. 7 with the guide shield and blow-off air tube parts removed to better illustrate details.

FIG. 31 is a fragmentary end elevational view of the entrance guide of station No. 7 looking in the direction of arrow 31 in FIG. 30.

FIG. 32 is a fragmentary vertical sectional view taken on the line 32-32 of FIG. 30.

FIG. 33 is a fragmentary vertical sectional view taken on the line 33-33 of FIG. 30.

FIG. 34 is a fragmentary plan view of the strip stock after it has been severed in the cut-off operation of station No. 7.

FIG. 35 is a fragmentary front elevational view of a portion of station No. 7 illustrating the strip coiling anvil and associated bending pad in the open position thereof.

FIG. 36 is a fragmentary end elevational view of actuating linkage in station No. 7 as viewed on the line 36-36 of FIG. 30.

FIG. 37 is a fragmentary front elevational view of the apparatus of stations Nos. 8 and 9 of the machine.

FIG. 38 is a fragmentary front elevational view of a portion of the station No. 8 apparatus shown in FIG. 37 but illustrating the pusher members in closed position embracing the entrance cone of this station.

FIG. 39 is a side elevational view of the apparatus of station Nos. 8 and 9.

FIG. 40 is a fragmentary horizontal sectional view taken on the line 40—40 of FIG. 37 illustrating a portion of the apparatus of station No. 9.

FIG. 41 is a horizontal sectional view taken on the line 41—41 of FIG. 37.

FIG. 42 is a horizontal sectional view taken on the line 42—42 of FIG. 37.

FIG. 43 is a fragmentary horizontal section of the shot pin and slide parts of FIG. 42 but with the shot pin shown in engaged position with the slide.

FIG. 44 is a fragmentary side elevational view illustrating the punch, clamp and die components of station No. 8, FIG. 44 being partially taken in vertical center section and enlarged over FIG. 39.

FIG. 45 is a fragmentary vertical sectional view taken on the line 45—45 of FIG. 44.

FIG. 46 is a fragmentary horizontal sectional view taken on the line 46—46 of FIG. 44 but greatly enlarged thereover.

FIG. 47 is a fragmentary vertical sectional view taken on the line 47—47 of FIG. 46.

FIG. 48 is a fragmentary plan view of a portion of the parts shown in FIG. 46 but with their position changed to illustrate the joint trimming and initial bending action.

FIG. 49 is a view similar to FIG. 48 showing the parts at the completion of the trim and bending stroke.

FIG. 50 is a fragmentary side elevational view of the left-hand clamp member shown in FIGS. 46, 48 and 49.

FIG. 51 is a fragmentary side elevational view of the right-hand shearing and bending punch shown in FIGS. 46, 48 and 49.

FIG. 52 is an end elevational view of the left-hand forming die shown in FIGS. 46, 48 and 49.

FIG. 53 is a fragmentary perspective view of one end of the spacer-expander illustrating the end joints thereof after being trimmed and bent in station No. 8.

For purposes of facilitating description and not by way of limitation, the machine 100 of the present invention is illustrated with the proper dies for forming the piston ring spacer-expander illustrated in the aforementioned United States Warrick U.S. Pat. No. 3,477,732, particularly the spacer-expander 58 shown and described in conjunction with FIGS. 1—5 inclusive thereof and with the end joint construction shown and described in conjunction with FIGS. 14—16 inclusive thereof, this patent being incorporated herein by reference and hence spacer-expander 58 thereof not being described herein.

GENERAL ARRANGEMENT

Machine 100 of the present invention is shown substantially in its entirety in FIG. 1 and generally consists of a punch press similar in part to that shown, described and claimed in the aforementioned U.S. Burns et al. U.S. Pat. No. 2,925,847, which is incorporated herein by reference for a detailed disclosure of certain portions of the machine identified in more detail hereinafter. Machine 100 has a base 102 which supports a frame 104 and a motor 106 on frame 104 which drives a flywheel 108 through a belt 110. Flywheel 108 is connected by a clutch 112 with the crankshaft 114 of the press. Clutch 112 is of the positive drive, electric throw-out type. Shaft 114 is journalled on the frame of the machine in bearings 116. A pair of magnetic brakes

118 are arranged around shaft 114 and when electrically energized operate to seize shaft 114 when the circuit to the brake is opened. Shaft 114 has three crank portions to which the upper ends of connecting rods 5 120, 122 and 124 are individually pivotally connected. Rods 120, 122 and 124 are connected respectively at their lower ends to associated rams 126, 128 and 130 which are guided for vertical reciprocating movement on frame 104 in ways formed in three sets of guide plates 132, 133 and 134 respectively.

As set forth in more detail hereinafter, ram 126 operates a piercing die assembly 136 of station No. 1 and a blanking and notching die assembly 138 of the station No. 2. Ram 128 operates a foot bending and joint notching die assembly 140 of station No. 3 and a leg bending die assembly 142 of station No. 4. Ram 130 operates a strut bending and strip curling die assembly 144 of station No. 5 and, also, through a linkage 804, operates a coiling and cut-off die assembly 146 of station No. 7. The end joint trimming and bending die assembly 148 of station No. 8 is powered by pneumatic rams synchronized with the operation of the press by a suitable counting and control mechanism as described in more detail hereinafter.

The end of shaft 114 remote from flywheel 108 carries a disc 150 to which a link 152 is eccentrically connected for driving a strip feeder 154 through a bell crank 156. A suitable commercially available magnetic pick-up assembly 160 is provided for counting revolutions of shaft 114 to develop one signal per each vertical reciprocation of the rams 126, 128 and 130 through their simultaneous mechanically synchronized working strokes. Pick-up 160 has a rotating part 162 secured to shaft 114 for rotation therewith and a stationary part 164 secured to the stationary structure of the end bearing 116. Pick-up 160 provides the input signal to a suitable counter control (not shown), such as that sold under the trademark "DYNAPAR" made by the Louis Allis Division of Litton Industries at the Digital Center in Gurnee, Illinois and identified as a Digital Process Controller Type 5X2-58-X-1. This controller operates through the signals derived from pick-up 160 to initiate the cut-off operation as well as the air blast at station No. 7. This occurs in response to an output signal developed by storing the number of counts in the digital memory of the controller corresponding to the number of increments of advance of the strip 170 being worked in machine 100 required to pass a given length spacer-expander through the coiling die of station No. 7. Also, this control further provides an output signal for actuating the pusher fingers of station No. 8 after allowing a time delay (corresponding to a given number of counts) for the severed spacer-expander to drop onto the nose cone of station No. 8. The remaining motions in stations Nos. 8 and 9 are controlled by conventional limit switches and solenoid valve circuitry (not shown) associated with the moving parts of this station as described in more detail hereinafter.

The counter control is also adapted to generate a control signal for causing a transverse shuttle motion of die assemblies 136, 138 and 140 of stations Nos. 1, 2 and 3 as an end joint zone of the strip stock being fed therethrough comes into successive registry with the respective die assemblies, as set forth in more detail hereinafter.

In general, the operation of machine 100 is as follows:

Steel strip material 170, preferably stainless steel of the A.I.S.I. 301 type, is pulled from a coil 172 by feeder 154 and pushed with an intermittent advance and then pulled back to locate it stationarily at station No. 1 where the punching die assembly 136 forms the six transverse slots 174, 176, 178, 180, 182 and 184 shown in FIG. 2 per each working stroke after each incremental advance of the strip. These slots are spaced equally lengthwise of the strip and form a continuous row running the length of strip 170 required to form a single spacer-expander 58 except for the end joint portions 186 of strip 170 located between each spacer-expander wherein the end joint tabs 275 are to be formed. In this area 186 two shorter longitudinally aligned transverse slots 188 and 190 (FIG. 2) are punched in the space otherwise taken by the fourth slot 180. The two separate punching operations performed at station No. 1 are obtained by providing two sets of piercing punch and die means arranged in tandem in a shuttle die assembly 84 movable perpendicularly to the direction of strip feed in the manner set forth in the aforementioned Burns et al. U.S. Pat. No. 2,925,847 relative to the piercing die assembly 84 described therein.

Strip 170 then advances to station No. 2 where a portion of the strip defined between slots 174 and 176 is blanked out and the portion of the next strip between slots 176 and 178 diagonally offset from the first blanking is also blanked out, to thereby define in the plane of strip 170 the material from which spring legs 76 and 78 are subsequently bent. This blanking is performed by a first die set of die assembly 138 which contains four punches to simultaneously form in one stroke of the punch two legs 76 and two legs 78 in two adjacent pitch lengths (identified as "2P" in FIG. 3) in keeping with the two-pitch increments of strip advance imparted by feeder 154. As in station No. 1, station No. 2 contains two die sets in a tandem shuttle arrangement to perform the leg blanking operation and then a first notching operation in joint area 186 when this area comes into registry with the second station (see FIG. 3).

The strip then advances through station No. 3 wherein die assembly 140, also a dual tandem shuttle die assembly, bends up the feet 82 and 84 on legs 76 and 78 respectively (see FIG. 4). When the joint area 186 comes into registry with station No. 3, the rear die set performs a notching operation to form the two cross-bars 281, one for the end joint tab 275 for the trailing end of one spacer-expander and the other for tab 275 for the leading end of the successively adjacent spacer-expander. These two spacer-expander lengths remain joined by a median strip 192 (FIG. 4).

The strip then advances through station No. 4 wherein legs 76 and 78 are bent upwardly from the plane of the strip (FIG. 5). Thereafter, the strip advances through station No. 5 wherein struts 74 are bent progressively by a row of punches of the punch and die assembly 144, the strip being simultaneously curled to bring the marginal bands 70 and 72 towards one another to thereby form the channel-shaped configuration of the strip (FIG. 22). The strip material then passes through the induction heater of station No. 6 to station No. 7 where the strip is coiled into a circular configuration and then cut off in the joint area.

The severed spacer-expander ring then is transferred to station No. 8 wherein die assembly 148 trims off the flash remaining on the joint tab and bends the tabs 275 to their final position. At the last station No. 9, the

completed spacer-expander 58 is pushed downwardly onto a tube loader which stores up a given quantity of the rings in synchronism with the operation of station No. 8. The loading tube is removed periodically when full to transfer the stack of rings 58 to further finishing and/or packaging operations as desired.

STRIP FEEDING MECHANISM

Referring to FIG. 1, the strip feeder 154 may be any standard unit conventionally employed for feeding strip stock intermittently by predetermined increments, such as a commercial "slide feed" manufactured by U.S. Baird of Stratford, Connecticut. Another suitable feeder is that disclosed in the aforementioned Burns et al. U.S. Pat. No. 2,925,847. Feeder 154 thus has a clamp mechanism which may be set to frictionally clamp and advance strip 170 a given distance for each revolution of the crankshaft 114 of the press 100. Feeder 154 also has a strip pull-back mechanism for retracting the strip a short distance after its advance stroke in order to accurately locate strip 170 in registry with the respective work stations. This is done by a stock locator mechanism 200 which includes a pivoted pawl stop of the type disclosed in U.S. Pat. No. 2,925,847. The pawl is adapted to drop into each successive fourth slot 180 (and into slots 188 and 190 when area 186 registers with locator 200) during the pull-back of the strip to thus locate the strip with reference to these slots through work stations Nos. 1-7 inclusive of the machine.

Preferably, strip 170 is passed through a lubricating tank 202 in advance of the feeder 154 by passing the strip over a first guide roll 204, under a spring biased roll 206 carried on the end of the pivoted bell crank 208, and up over an exit guide roll 210. The strip 170 then passes through a suitable lubricant stripper 212 and thence between the entrance guide rolls 214 of feeder 154.

In accordance with one feature of the present invention, machine 100 employs only one strip feeder 154 and this is arranged upstream of all the work stations so that the strip stock is pushed from this one feeding point as a continuous strip up to and through station No. 7. This is accomplished by providing a substantially continuous guideway for the strip from feeder 154 through station No. 7 in which the strip slides and in which it is yieldably restrained from buckling in a direction perpendicular to the plane of the strip. The structure of this guideway includes a guide 216 between feeder 154 and station No. 1, a guide 218 between stations Nos. 1 and 2 and a guide 220 between stations Nos. 2 and 3. These guides are relatively simple in construction and hence not shown in detail herein; i.e., they merely consist of two plates, a lower plate stationarily fixed to the frame of the machine and an upper plate resiliently clamped to the lower plate. The passage through the guideway is defined by a groove in the lower plate, the upper plate serving as a yieldable cover for the same. However, the next guide 222 associated with infeed and throughfeed of station No. 4 is more complex and will be described in more detail in conjunction with station No. 4.

STATIONS NOS. 1 AND 2

Inasmuch as the structure and operation of a dual tandem die assembly capable of shuttling in a direction perpendicular to the strip feed is set forth in the afore-

mentioned Burns et al. U.S. Pat. No. 2,925,847, the details of this structure will not be described herein. Suffice it to say that in station No. 1 a single lower die shoe and upper die shoe respectively carry a die holder and a punch holder. The die holder is adapted to carry a front die set and a rear die set, and similarly the punch holder carries a front punch set and a rear punch set constructed pursuant to conventional punch and die tooling techniques as will be readily understood by one skilled in the art and from the description of station No. 4 hereinafter. The front punch and die set is adapted to pierce the six slots 174-184 (FIG. 2) and the rear punch and die set is adapted to punch the two slots 188 and 190 in the joint area 186 of the strip. These front and rear punch and die sets are carried as a unitary assembly in the upper and lower shoes of die assembly 136, and both sets close and open simultaneously with each vertical reciprocation imparted to die assembly 136 by ram 126. Normally the front punch and die set is positioned in registry with strip 170 to punch the six slots after each advance of the strip, this operation being repeated twenty times for a spacer-expander 58 having forty sets of spring legs 76 and 78. Then, through the operation of an air cylinder as set forth in U.S. Pat. No. 2,925,847, the upper and lower shoes of die assembly 136 are shifted transversely of the strip to bring the rear set into registry with the strip during the period that the die assembly 136 is open and while strip is being advanced and located for the next working stroke. Hence on the next reciprocation of ram 126 strip 170 is operated on in the joint area 186 by the rear die and punch set to produce the slots 188 and 190. After the die is opened, the control mechanism again shifts it rearwardly to bring the front punch and die set back into registry with strip 170 to resume the sequential punching of a row of 120 (in the example above) cross slots 174-184 required in the next length of strip 170 to form the next successive spacer-expander.

At station No. 2 the same type of dual punch and die shuttle construction is employed in die assembly 136, i.e., front and rear punch and die sets mounted side by side in a single punch holder and die holder respectively, and respectively carried in the upper and lower shoes which are mounted for sliding movement transversely of the strip under the control of an air cylinder as set forth in U.S. Pat. No. 2,925,847. Thus while the front dies of assembly 136 are punching the slots 174-184 the front punch and die set of die assembly 138 is blanking out the four spaces in each two pitch increment of advance of the strip, as shown by the spaces in the length of strip identified as 2P in FIG. 3. This completes the blanking of the strip to define the material which forms the legs 76 and 78, and will occur for 20 working strokes in succession corresponding to the twenty working strokes of the front punch and die set of die assembly 136 mentioned above. Then, when the die assemblies are open and as the end joint area 186 comes into registry with die assembly 138, which may or may not occur at the same time, the next succeeding joint area 186 registers with die assembly 136, the upper and lower shoes of die assembly 138 are shifted forward to bring the rear punch and die set into registry with the strip. Preferably the station spacing is less than the strip length of a spacer-expander and hence die assemblies 136 and 140 do not shuttle simultaneously with the forward shuttling of die assembly 136. Hence when slots 188 and 190 are being punched

in one joint area 186 in station No. 1, the next preceding area 186 will already have been punched in station No. 2 to form the six holes 226 shown in FIG. 3 and will have been advanced beyond station No. 2.

5 The shuttling of die assemblies 136, 138 and 140 occur independently of one another due to their associated shuttle air cylinders and solenoid valves being individually controlled from the aforementioned counter control. The memory unit of this control is set so that 10 on the count numbers corresponding to registry of zone 186 with each successive shuttle station, individual actuating signals are generated for such stations. This enables the spacing of the shuttle stations relative to one another in the direction of strip feed to be independent 15 of the strip length of a spacer-expander being formed in machine 100. However the shuttle motion of a given station does remain in synchronism with the alternating strip feed and reciprocation of the die assembly of such station due to the input signal from unit 160 to the 20 counter control being taken from the mechanical drive train controlling these motions. The shoes of die assembly 138 are then shifted rearwardly to once again bring the front punch and die set into registry with the strip simultaneously with this action occurring in die assembly 136.

STATION NO. 3

The die assembly 140 of station No. 3 is, like those in stations Nos. 1 and 2, a dual, skip function front and rear tandem arrangement of two punch and die sets carried in common punch and die holders in a single pair of upper and lower die shoes to perform two functions on the strip, die assembly 140 reciprocating vertically with die assemblies 136 and 138. The front punch and die set is adapted to bend the feet 82 and 84 on legs 76 and 78 respectively and hence will operate repetitively through 20 strokes in the example set forth above as the 22-pitch increments successively register with the front punch and die set. Preferably, the front die set has a two-part die forming two V-shaped protrusions with the crest of one aligned with the tips of legs 76 and 78 in one pitch and the crest of the other aligned with the tips of legs 76 and 78 in the next pitch. The front punch set has two complementary V-shaped grooves designed to impart, superposed over the die projections and upon closing of die assembly 140a, slight upward bend to the free ends of two legs 76 and two legs 78, thereby forming the inclination of the feet 82 and 84 relative to their associated legs 76 and 78, as best seen in FIGS. 5 and 22. Die assembly 140 has the same spacing from die assembly 138 in the direction of strip advance as does die assembly 138 from die assembly 136. Hence die assembly 140 will form feet 82 and 84 in one spacer-expander length simultaneously with the blanking operation of die assembly 138 and with the blanking of the slots in die assembly 136 as these operations are being performed on the next two successive spacer-expander strip lengths.

When a joint area 186 registers with die assembly 140, the skip function of die assembly 140 occurs in response to the associated counter control signal, thereby bringing its rear punch and die set, while open, forward into registry with the strip to operate on the joint area. In station No. 3 the rear die set consists of a two-part joint die mounted in the die holder of the lower shoe providing two side-by-side openings extending in the direction of strip feed and aligned with strip margins 70

and 72. Two punches mounted in the punch holder in the upper die shoe descend into these openings to thereby blank out the side margins 70 and 72 of strip 170 in the joint area 186, and also trim the material connected to the end tab portions 281 as shown in FIG. 4 by the finished blanking in area 186 of the strip.

Die assemblies 136, 138 and 140 are each individually adjustable in the direction of strip feed as required to accommodate setup changes required to produce different size spacer-expanders. This lengthwise adjustment is accomplished with respect to the upper die shoe with a conventional double gib connection to the associated punch rams and by a sliding mount of the lower die shoe and its associated bed plate as disclosed in the aforementioned Burns et al. U.S. Pat. No. 2,925,847.

It is also to be understood that die assemblies 136 and 138 and 140 are preferably constructed with a spring-biased stripper plate which is slidably mounted on the two guide pins of the die shoes for limited vertical movement adjacent the lower shoe. The stripper plates have openings through which the punches of the upper shoes pass on their downstroke and into which the lower ends of the punches are retracted on their upward stroke to insure that the strip 170 is cleared from the punch, as will be well understood by those skilled in the art.

STATION NO. 4

The die assembly 142 of station No. 4 and the associated strip feeding guide 222 are shown in detail in FIGS. 6, 7, 8, 9, 10, 11, 12 and 13. As best seen in FIG. 5, strip 170 is operated upon in this station to bend legs 76 and 78 upwardly from the plane of the strip to their final inclination relative to the associated side margins 72 and 70 of the strip.

Referring first to die assembly 142 as shown in FIG. 6, it includes a block 230 slidably mounted on a bolster 232 of press 100 and setup adjustment of the bolster in the direction of strip feed is provided by an adjusting screw 234, associated stationary support 236 and adjusting knob 238. Slide block 230 carries a lower die shoe 240 of die assembly 142 in a transverse dovetail to accommodate transverse movement of assembly 142. Shoe 240 has two upright guide posts 242 and 244 (FIG. 7) on which a stripper assembly 246 and an upper die shoe 248 (FIG. 6) of die assembly 142 are guided for vertical movement. Upper shoe 248 has a pair of gib plates 250 and 252 formed with inwardly projecting flanges 254 and 256 which form a guideway on the upper face of shoe 248 in which the lower, flanged end part 258 of a pin 260 (FIG. 1) is arranged. The upper end of pin 260 is threaded into ram 128 (FIG. 1) so that as the ram reciprocates vertically upper die shoe 248 is caused to travel vertically on posts 242 and 244. Gibs 250 and 252 as well as block 230 provide the horizontal ways transverse to strip feed which accommodate the aforementioned front-to-rear shuttle movement of the die assembly 142, this same construction being employed in stations 1, 2 and 3 to accommodate the dual function shuttle die assemblies of these first three stations. Although station No. 4 has the capability of dual function, it is not so used in making spacer-expander 58 but rather merely contains one punch and die set for performing the one leg bending operation on strip 170.

Lower shoe 240 carries a two-part die holder 262 suitably fastened to shoe 240 and adapted to clamp a horn die 264 therein. Upper shoe 248 likewise has a two-part punch holder 266 secured thereto in which is clamped a punch 268. Stripper assembly 246 comprises a cross plate 270 carrying bushing collars 272 and 274 which guide the stripper on posts 242 and 244 respectively. Plate 270 projects beyond the entrance and exit of the shoes of die assembly 142 as best seen in FIG. 6. 10 Plate 270 has a central aperture 276 through which the upper end of horn die 264 projects with a close clearance. Stripper 246 also comprises a pair of guides 276 and 278 which are mounted on a recessed platform area of plate 270. As best seen in FIG. 7, guides 276 and 278 provide laterally flanking sidewalls 277 and 279 for closely guiding strip 170 though die assembly 142 so that it is laterally centered for accurate registry with punch 268 in horn die 264. However, guides 278 and 279 are notched out to accommodate travel of 15 punch 268 to its closed position (FIG. 8). Stripper 246 is yieldably biased to the raised position thereof shown in FIG. 7 by a pair of compression coil springs 280 and 282 when die assembly 142 is opened (FIG. 7), the raised position of stripper 246 being determined by engagement of plate 270 with the head of an adjustable stop stud 284 extending through plate 270 and screwed into shoe 240.

As best seen in FIGS. 10, 11 and 12, horn die 264 has two pairs of laterally offset bending horns 286-288 and 290-292 each provided with a relatively large radius nose 294 at the upper end of the outwardly facing surface of the horn. Horns 286 and 290 at the front side of die 264 are adapted to register with the two legs 76 in a two-pitch increment of strip 170, and the companion horns 288 and 292 similarly register with the opposite legs 78 of this two-pitch increment. Punch 268 has a dovetail-shaped cutout 296 defined by a pair of clamping feet 300 and 302 which are vertically aligned with the respective side marginal bands 72 and 70 of strip 170.

In the operation of station No. 4, strip 170 is advanced intermittently through station No. 4 while the die assembly is in full open position as shown in FIGS. 6 and 7. In this condition stripper 246 is in its uppermost position and hence provides a platform to slidably support strip 170 above and clear of the horns of die 264, the upper ends of the horns thus being recessed below the guide surface 304 (FIG. 10) extending centrally along plate 270. As upper shoe 248 descends during initial closing movement of die assembly 142, feet 300 and 302 of punch 268 first strike the upper surface of the marginal bands 70 and 72 of strip 170 as shown in FIG. 10 and then clamp the bands against the slightly upwardly inclined surfaces 306 and 308 of the guideway on stripper plate 270. Due to the strong upward force exerted by springs 280 and 282, strip 170 is firmly clamped between punch 268 and plate 270 prior to initiating bending of legs 76 and 78. As upper shoe 248 continues its downward closing movement, punch 268 carries stripper 246 along with it and thus pulls strip 170 downwardly over the stationary horns 286-292 of die 264, thereby bending legs 76 and 78 upwardly from the flat position thereof shown in FIG. 10 to the bent position thereof shown in FIG. 11 as die assembly 142 reaches closed position (FIGS. 8, 11 and 12).

On the upstroke of shoe 248, springs 280 and 282 press plate 270 upwardly so that it tracks the rising

movement of punch 268 to thereby pull strip 170 clear from punch 264. Upward movement of plate 270 ceases when it hits the head of stop stud 284 as shown in FIG. 7, but punch 268 continues moving upwardly until shoe 248 reaches its fully raised position shown in FIGS. 6 and 7. Thus in a single cycle of die assembly 142 two pairs of legs 76 and 78 are bent to their final inclination relative to their respective side marginal bands 72 and 70 as shown in FIG. 13.

Strip 170 is then advanced another two-pitch increment to bring two more pairs of legs into registry with the horns of die horn 264, and the cycle repeated. Die assembly 142 thus cycles repetitively to bend up forty legs 76 and 78 in twenty successive strokes in the example given previously. When a joint area 186 comes into registry with punch 268 and die 264, die assembly 142 is not shifted transversely of the strip but rather operates through another cycle. However, this does not produce any working of strip 170 because horns 268-292 do not engage any material in joint area 186.

Station No. 4 also incorporates a vertically movable guideway which includes the aforementioned guide 222 and also the guiding surfaces of plate 270 and guides 276 and 278 of stripper assembly 246. Guide 222 cooperates with stripper 246 to track the up and down motion of strip 170 as it is worked in die assembly 142. Guide 222 comprises a pivoted guide finger assembly made up of a base 310 (FIG. 6) having an arm 312 which nests between the upright arms 316 and 318 of a support 320 (FIGS. 6 and 9) stationarily secured to bolster 232 adjacent the exit end of station No. 3. Arm 312 is pivotally mounted on a pin 322 extending horizontally through arms 316 and 318. Arm 312 has an inclined entrance surface 324 (FIG. 6) which extends upwardly in the direction of travel of strip 170 to merge with a flat horizontal surface 326 which extends to the free end 328 of arm 312 (FIGS. 6 and 9). Base 310 also has a pair of flanges 330 which extend downwardly beneath a pair of lateral extensions of arm 312, one on either side of guide surface 326. Flanges 330 have guideways on their outer sides adapted to receive side plates 332 and 334 respectively, as shown in FIG. 9. Side plate 332 is secured by a screw 336 to the front flange 330 of arm 312, and side plate 334 is secured by screw 338 to the rear flange of the arm.

A base extension 340, also having a central platform 341 and a pair of dependent flanges 342 on either side of the platform, is secured to base 310 by a pair of screws 344 and 346 (FIGS. 6 and 9) which extend through horizontal slots in side plates 332 and 334 respectively and thence into the flanges 343 of extension 340. Base extension 340 thus can be shifted relative to base 310 in the direction of strip travel. The upper surfaces 350 of platform 342 is flush with and provides a horizontal extension of surface 326 of arm 312. Platform 342 terminates adjacent the entrance end of the strip guideway formed by ways 304, 306 and 308 on stripper plate 270 and by the associated walls 277 and 279 of guides 276 and 278.

A cover 352 complementary in shape to base 310 overlies the same and is secured thereto by screws 354 and 356. Thus cover 352 and arm 312 of base 310 together define a guideway through which the strip 170 slidably extends and is confined against lateral and up and down movement as the strip is pushed through the guide 222. Base extension 340 also has a cover 358 secured to the flanges of extension 340 by screws 360 and

362 (FIG. 9). Cover 358 thus overlies surface 350 to likewise define a strip guideway which is an extension of the guideway between base 310 and its cover 352.

In addition, cover 358 has an arm 364 projecting horizontally therefrom over the guideway of the stripper plate 270. Arm 364 has a narrow vertical slot 366 running lengthwise of the arm and which is open at its lower end to receive a pressure blade 368. Blade 368 has a threaded stud 370 affixed thereto which projects upwardly through a hole in cover 358 to receive a nut 372 to thereby secure the blade snugly against the top wall of slot 366. As best seen in FIGS. 6 and 12, blade 368 has a notch 374 in its lower edge extending somewhat beyond either end of the horn die 264 to provide clearance for the upward bending of legs 76 and 78 in die assembly 142. The free end 376 of blade 368 terminates just short of the entrance end of die assembly 144 of station No. 5. Blade 368 is relatively narrow and rides slidably on the center of the struts 74 and feet 82, 84 of strip 170 as the same enter die assembly 142 and then on the struts alone after strip 170 leaves die 264. A tension coil spring 380 is secured at its opposite ends to support 236 and extends up and over cover 358 to thereby yieldably bias pressure blade 368 downwardly onto the upper surface of strip 170. The sliding contact of blade 368 with strip 170 thus provides the support for the free end of the pivoted guide 222.

In operation, guide 222 will pivot up and down about the horizontal axis of pin 322 as pressure blade 368 follows the raising and lowering of strip 170 on the guideway of stripper plate 270 as stripper 246 is reciprocated vertically in response to closing and opening of die assembly 142 as described previously. Thus, with this arrangement strip 170 is maintained under close control while being gently flexed or bowed through a relatively large distance lengthwise of the strip, i.e., approximately from pivot pin 322 over to the entrance to die assembly 144. Since very little of strip 170 is left unconfined the same is reliably restrained from any tendency to buckle upwardly or downwardly despite the longitudinal compressive stress imparted by feeder 154 to the strip when pushing it during the step-by-step strip advance. Nevertheless, in keeping with the two-part yieldable cover construction of the previous guides 216, 218 and 220, guide 222 cooperates with stripper 270 to form another two-part guideway wherein the entire guide 222 functions as the yieldable cover relative to stripper plate 270.

STATION NO. 5

The construction and operation of die assembly 144 of station No. 5 is shown in FIGS. 14-28 inclusive. Referring first to FIG. 14, as supplemented by FIGS. 15 and 23-27 inclusive, die assembly 144 has an upper shoe 400 guided for vertical reciprocation on four posts 402, 404, 406 and 408 mounted in a lower die shoe 410. Shoe 410 is suitably secured on bolster 232 by an adjustment mechanism 412 (FIG. 1) such as that disclosed in conjunction with FIG. 10 of the aforementioned U.S. Pat. No. 2,925,347 so that die assembly 144 can be adjusted in the direction of feed of strip 170. Upper shoe 400 is connected to the ram pin 414 which in turn is secured to ram 130 so that shoe 400 is reciprocated vertically by ram 130 in synchronism with the preceding stations Nos. 1-4 inclusive.

Shoe 400 carries a two-part punch holder 416-416' having a series of ten progressive strut bending punches

A-J inclusive secured therein. The first six punches A-F all are dependent integrally from one common carrier 148 which is T-shaped in cross-section (FIG. 25) and which is clamped between the front holder 416 and its companion rear holder 416'. The last four punches G-J inclusive each have individual carriers 420, 422, 424 and 426 also T-shaped in cross-section and clamped between holders 416 and 416'. Each of the 10 punches A-J is of equal length so that their lower free ends are flush with one another along a horizontal line. The first six punches A-F also are identical in cross-sectional profile as indicated by illustrations of punches B, D and E respectively in FIGS. 17-19 inclusive. However, the last four punches G, H, I and J are narrower progressively across their lower ends in their horizontal dimension perpendicular to the direction of strip feed.

Lower die shoe 410 are a relatively wide central trench extending in the direction of strip feed, the trench being defined by floor 430 and side walls 432 and 434 (FIGS. 14-23 and 25). A pair of die holders 436 and 438 are mounted against walls 432 and 434 and seat on bottom wall 430. Holders 436 and 438 retain a set of strut bending dies made up of five front pieces and five rear pieces which function as forming anvils in cooperation with punches A-J inclusive in the bending of the struts 74 and strip 170. The front and rear forming anvils 440 and 442 respectively (FIG. 25) are slightly longer than the space occupied by the first six punches A-F in the direction of strip feed as shown in FIG. 14. Thus, the trailing end 444 of the rear forming anvil 442 is disposed slightly in advance of punch G, and leading end 446 of anvil 442 is disposed slightly in advance of punch A (FIGS. 14 and 24). The horizontal spacing between anvils 440 and 442 is uniform along their length and each anvil has smoothly curved upper inner edges 448 and 450 respectively (FIG. 17) having a radius of approximately 0.060 inch. As best seen in FIGS. 14 and 16, the upper edges 448 and 450 of dies 440 and 442 are inclined slightly upwardly from the horizontal in the direction of strip feed on the order of 2°8' to 2°17', depending on the pitch length of the spacer-expander 58 being produced in machine 100, i.e., a ring 58 having, for example, a pitch length of 0.310 inch requiring the smaller taper angle and a ring of smaller pitch length of, say 0.290 inch, requiring the larger taper angle.

The last four sets of horn dies 454-468 are arranged in laterally spaced pairs associated with each of the last four punches G, H, I and J. The front and rear horn dies 454 and 456 respectively (FIGS. 24 and 26) are located adjacent the trailing ends 444 of dies 440 and 442, and the remaining pairs of horn dies 458-460, 462-464 and 466-468 are successively abutted on opposite sides of their associated punches G, H, I and J respectively. Each of the horn dies 454-468 has an upright bending horn 454', 456', etc. respectively, each of which is just slightly wider in the direction of strip feed than its associated punch and is centered in said direction of the center line of the punch, as best seen in FIG. 16. Each punch in turn has a dimension in the direction of strip feed just slightly larger than the corresponding dimension of struts 74 of strip 170. Hence, the spacing from one die horn 456' to the next die horn 460' in the direction of strip feed provides a clearance space to accommodate the previously bent legs 76 and 78 which are caused to change from their upright posi-

tions imparted in station No. 4 to their mutually crossed positions as they leave die assembly 144, as illustrated in FIGS. 21 and 22, due to the progressive curling of the side margins 70 and 72 of the strip towards one another in station No. 5. Hence legs 76 and 78 in the closed position of die assembly 144 are disposed below the level of the upper surface of the die horns 454', etc.

It also is to be understood that punches A-J are 10 equally spaced lengthwise of strip 170 so as to register with 10 successive struts 74. By way of explanation, the odd-numbered struts are identified as 74' and the even-numbered struts as 74. Due to the two-pitch length increments of intermittent advance of strip 170 described 15 previously, struts 74' will be worked to impart progressive bending thereto only by the odd-numbered punches A, C, E, G and I, whereas struts 74 will be bent progressively by being worked only by the even-numbered punches B, D, F, H and J, in that order. It 20 also is to be noted that the horns 454'-468' are identical in configuration and are positioned at the same elevation relative to one another so that their upper surfaces are flush with a horizontal line which coincides with the elevation of the trailing end of die horns 440 and 442. However, there is a transition in the direction 25 of strip feed with respect to the lateral spacing of the horns 454' and 456' of each associated pair of horn dies 454-468. Thus, horns 454' and 456' are spaced more closely together than horn dies 440 and 442, as 30 seen by comparing FIG. 20 with FIG. 19. This lateral spacing of the die horns decreases progressively, horns 458' and 460' being slightly more closely spaced than the preceding horns 454' and 456', and so on, this narrowing again being seen in comparing FIG. 20 to FIG. 35 21.

For example, the bending horns of dies 440 and 442 40 may have a lateral spacing of 0.1620 inch, whereas the spacing of horns 454' and 456' may be 0.1500 inch. The lateral spacing between the three sets of die horns 450 may be, for example, 0.1470 inch, 0.1325 inch and 0.1313 inch. Likewise, the distance across the lower 45 end of the first six punches A-F may be 0.1350 inch, and then the next four punches G-J may have respectively a corresponding dimension of, for example, 0.1245 inch, 0.1210 inch, 0.1080 inch and 0.1065 inch.

The lower die shoe 410 also carries a stripper stop plate 470 (FIGS. 14 and 26) which is secured to surface 430 in the middle of the trench and serves as a 50 spacer for the horn dies in shoe 410. Plate 470 also serves as an accurate bottoming stop for a movable stripper 472 which has an inverted T-shaped cross-section (FIG. 25) and is disposed for vertical reciprocating movement between the horn dies in shoe 410. Stripper 472 is biased upwardly by a pair of compression coil springs 474 and 476 (FIG. 14) which are 55 guided in bores 478 and 480 respectively of shoe 410 and on pins 482 and 484 projecting downwardly from the base of stripper 472. The lower ends of the springs bottom on adjusting screws 486 and 488. The lower 60 limit of travel of stripper 472 is determined by its base seating on the accurately machined upper surface of stop 470, and the upper limit of travel of stripper 472 is determined by the base of the stripper engaging horizontally aligned shoulders 490 and 492 of dies 440-468 (FIG. 26). As best seen in FIG. 24, the upright stem of 65 stripper 472 has a uniform width dimension in the portion extending between dies 440 and 442, and the stem

is narrowed in width at point between punches F and G to have smaller but uniform width in the portion extending between dies 454-468, this trailing portion being sized to fit closely between the last dies 466 and 468. The upper surface 494 of strip 472 thus extends horizontally past both ends of the row of punches A-J and associated horn lies to provide a smooth platform on which the struts 74 and 74' continuously ride and slide throughout their travel through the punches and dies of station No. 5. Surface 494 also supports struts 74 and 74' to provide a back-up punch cooperating with the upper punches A-J during the closing, working stroke of the die assembly 144.

Stripper 472 carries a paddle-like extension 496 cantilevered from its left end as viewed in FIG. 14. Paddle 496 extends outwardly beyond the entrance ends of the shoes 400 and 410 toward the preceding station No. 4 to serve as a vertically movable floor of a guideway for strip 170 which is defined within a multi-part guide block 498 secured in the entrance end of the trench in lower die shoe 410. The upper surface 500 of paddle 496 is flush with the upper surface 494 of the stripper 472. The entrance to the guide block 498 includes a generally T-shaped part 502 (FIG. 15) with a central slot defined by opposite side walls 504 and 506. Walls 504 and 506 are spaced to have a close clearance fit with strip 170 in the condition thereof shown in FIG. 5 as it leaves station 4 to maintain the strip aligned on center as it enters the punch and die area of the die assembly 144.

Guide block 498 also has a cover 508 with a central slot in its undersurface (FIGS. 14 and 15) defined by an upper wall 510 and a pair of vertical side walls 512 and 514 slightly inset from the associated walls 504 and 506 of the slot in part 502. The undersurface 516 of cover 508 defines a pair of shoulders 518 and 520 which overlie the side margins 70 and 72 respectively of band 170. Hence in the raised position of stripper 472 and associated paddle 496, strip 170 is confined closely yet slidably in the guideway, margin 70 having a close vertical clearance between the upper surface 500 of the paddle and shoulder 518, margin 72 likewise having a close clearance vertically between surface 500 and shoulder 520, and legs 76 and 78 just clearing at their upper ends top wall 510 of the guideway and laterally just clearing side walls 512 and 514 of the guideway. Hence, when die assembly 144 is raised to open position, strip 170 is confined closely in guide block 498 to restrain it from buckling as it is placed under compression when pushed to advance it into die assembly 144.

Die assembly 144 also has a stationary upper stripper and guiding structure associated with the punches A-J, as best seen in FIGS. 14, 23 and 25-28 inclusive. This structure includes a pair of stripper plates 522 and 524 which are secured by screws 526 and 528 (FIG. 23) to the upper surfaces of die holders 436 and 438 respectively. As best seen in FIG. 28, the rear stripper plate 522 has an inner side surface 530 aligned with the inner surface of holder 436 which extends in the direction of strip feed to an angled surface 532 which in turn terminates at an under cut surface 534 disposed adjacent horn die 468. Plate 522 also has a series of overhanging portions consisting of a first lip 536 extending adjacent punches A, B and C, a second lip 538 projecting farther towards the center line of the die set and extending in the vicinity of punches D and E, and a third lip 540 ex-

tending towards the center line beyond surface 534 and in the vicinity of punch J.

The front stripper plate 524 likewise has a first lip 542 somewhat shorter in length than lip 536, a further inwardly projecting lip 544 opposite lip 538 and somewhat longer in length, as well as side surfaces 546 and 548 corresponding to surfaces 530 and 532 of plate 522, and a lip 550 corresponding to lip 540.

Plate 522 has a notch 552 (FIG. 28) in which is mounted a rear stripper finger 554, a corresponding front finger 556 being mounted in a corresponding notch of front plate 524, as best seen in FIGS. 23 and 26. Each of the fingers 554 and 556 has a vertical flange 558 surmounted by an overhanging lip 560 (FIG. 26) extending in the vicinity of punches F and G (FIG. 14). Flange 558 and lip 560 form vertical and overlying horizontal guide surfaces respectively for strip 170 when it has an intermediate channel configuration while undergoing the curling transition from its shape shown in FIG. 19 to its shape shown in FIG. 20, as indicated in the phantom showing of a strut 74' and the associated marginal bands 70 and 72 in FIG. 26. The stationary stripper structure also includes a stripper rake 562 (FIGS. 14, 23 and 26) which is secured by screws 564 to the upper surface 566 of rear stripper plate 522. Rake 562 has four fingers 568, 570, 572 and 574 which overlie the path of travel of strip 170 in the vicinity of and immediately following punches G, H, I and J respectively (FIG. 14). These fingers extend toward the front of the die set past the front side of the underlying strip 170 so as to overlie the strip completely, as best seen in FIGS. 23 and 26.

Die assembly 144 also has an exit guideway for the strip 170 made up of a guide block 580 (FIGS. 14, 23, 24 and 27) and an associated cover 582 mounted on block 580, block 580 in turn being mounted in the trailing end of the trench in shoe 410. Block 580 has a vertically extending notch 584 (FIGS. 14 and 27) to accommodate the trailing end of stripper 472, the vertical back wall of the notch being chamfered at 586 where it leads into the flat horizontal upper surface 588 of block 580. Cover 582 has a notch in its underside centrally of the cover in alignment with the path of travel of strip 170 to define an exit guideway for station No. 5. As best seen in FIGS. 14 and 27, this guideway is defined by the side walls 590 and 592, top wall 594. The bottom surface of the guideway is defined by the upper surface 588 of block 580. Cover 582 has a guide rib 596 dependent in the center of the guideway so as to protrude downwardly between the now upright margins 70 and 72 of the curled strip 170. Rib 596 terminates at its lower free end just above the position of the crossed legs 76 and 78 of the strip when it is elevated to its raised position by stripper 472 in response to opening of die assembly 144. Preferably, the leading and trailing edges of the side walls 590 and 592 and of rib 596 are beveled to provide a flaring entrance and exit in the exit guide, as best seen in FIGS. 14 and 23.

In the operation of station No. 5, when die shoe 400 is raised to its open position (FIGS. 25 and 26), punches A-J are raised clear of the path of travel of strip 170 through its confined guideway in station No. 5. At this time stripper 472 and its paddle 496 are yieldably held in the raised position thereof shown in FIGS. 25-27 by springs 474 and 476. Hence surfaces 500, 494 and 588 are flush and form a substantially continuous horizontal supporting surface disposed at an eleva-

tion above the upper ends of the bending horns 488, 450 and 454'-468' of the lower dies 440, 442 and 454-468 and extending from the entrance to the exit of die assembly 144 on which the struts 74 and 74' of strip 170 can slide as it is intermittently advanced by feeder 154. The side and upper walls of the guideway in entrance block 498 in the stationary stripper structure associated with stripper plate 522 and 524 and in the exit block 580-582 cooperate with surfaces 500, 494 and 588 to slidably confine strip 170 as it undergoes its transition in shape from a flat condition (FIG. 5) to the U-shaped channel configuration seen in FIG. 22. Hence strip 170 remains accurately positioned laterally relative to the center line of the punches and dies of this station and is restrained from any tendency to buckle when it is being pushed.

When upper shoe 400 descends on its downward working stroke in synchronism with the upper shoes of the preceding stations Nos. 1-4, a row of 10 successive struts 74-74' will be struck simultaneously by punches A-J and pushed downwardly relative to die horns 448, 450 and 454'-468' in station No. 5. This will work the strip as partially indicated in FIGS. 17-21 to bend struts 74 and 74' progressively to the final channel configuration of FIG. 22. Considering the progression of one two-pitch length increment of strip 170 through the punches A-J and corresponding dies of die assembly 144, the leading strut 74 will be struck first by punch B and the adjacent trailing strut 74' will be struck simultaneously by punch A. Due to the upward taper of the bending horns 448 and 450 of dies 440 and 442, strut 74 will be bent upwardly to a slightly greater angle than strut 74' because the lower ends of punches A and B both bottom at the same horizontal elevation on their respective struts as determined by the bottomed position of stripper 472 on the stop 470 (FIGS. 14 and 16-21). When die shoe 400 is lifted, stripper 472 will rise with punches A-J under the pressure of its biasing springs, thereby pushing strip 170 upwardly clear of dies 440 and 442. Punches A and B continue rising after stripper 472 reaches the upper limit of its travel (FIGS. 25 and 26) until their lower ends rise above the undersurface of lips 536 and 542 of stripper plates 522 and 524. Thus, strip 170 will be cleared of punches A and B by the stripper lips should the same tend to cling to the punches when the same are lifted.

The strip 170 is advanced slightly more than a two-pitch length increment thereof and then pulled back slightly by feeder 154 against the locator pawls of mechanism 200, thereby bringing struts 74 and 74' into registry with and below punches D and C respectively and holding the strip stationary. Die shoe 400 then is closed again on its next working stroke. Again, due to the upward incline of the bending horns 448 and 450 of dies 440 and 442, leading strut 74 will be bent upwardly through another angular increment from that shown in FIG. 17 to that shown in FIG. 18 due to the greater relative penetration of punch D between the associated bending surfaces of dies 440 and 442. Likewise, trailing strut 74' will be bent upwardly by punch C and the associated die surface through another angular increment from the bend imparted at A, but the bend angle of strut 74' after being worked by punch C is still less than that to which strut 74 is worked by punch D. This alternate strip advance and strut bending sequence is repeated so that leading strut 74 is bent sequentially through further angular increments by

punches F, H and J and the associated portions of bending surfaces 448 and 450 of dies 440 and 442 and horns of dies 458-60 and 466-68. Likewise, the trailing strut 74' will be bent sequentially and progressively by punches E, G and I and their associated bending dies. Thus, each strut is worked by only five of the 10 punches in station No. 5 and in a sequential progression but always at an upward angle intermediate the progression of its adjacent strut. This insures a smooth, wrinkle-free transition in the side margins 70 and 72 of strip 170 as they curl upwardly from the planar condition of the strip shown in FIG. 5 to the channel configuration shown in FIG. 22. The incremental bending thus prevents a permanent ripple in margins 70 and 72 by limiting the bending stresses transmitted via the interconnecting margins of the strip from one strut to the next. However, each strut, although worked by different punches and dies than its neighbor, will have the same final configuration as it exits from the punches and dies of station No. 5.

Preferably, and in accordance with the method disclosed and claimed in the aforementioned co-pending application of Frank G. Warrick, the progressive bending of strut 74 and 74' is accomplished in a zone-working sequence as set forth in more detail in said co-pending application. Suffice it to say herein that the progressively deeper penetration of the struts relative to dies 440 and 442 as they are worked through punches A-F will cause the struts to bend about the outer corners of the respective punches in incremental segments in each of the two bends of a strut, starting with two spaced inner segments at each bend in the first punch and then working outwardly in the strut in the remainder of these first six punches. Then the sequence of progressive zone working is reversed as the struts are worked through the last four punches G-J. This is accomplished by making the penetration depth of punches G-J relative to die horns 454'-468 the same while making the lateral spacing of these horns progressively closer and at the same time making the lateral dimension of the nose of punches G-J progressively narrower. In this manner, bending stress is distributed around each of the two ends in each strut while obtaining a relatively small radius bend. In addition, the struts are worked to a channel configuration wherein edges 70 and 72 are inclined toward one another so as to converge at an angle of about 10° inwardly from the vertical, as shown in FIGS. 21 and 22. This is accomplished even through the relative motion of all of the punches and dies in station 5 is vertical and all the dies are immobile, i.e., there is no horizontal movement of the bending dies.

During the upward retracting stroke of shoe 400, strip 170 is cleared from punches C, D and E by lips 538 and 544, from punches F and G by lips 560 of fingers 554 and 556, and from punches H, I and J by fingers 568, 570, 572 and 574. At the same time, the side surfaces of flanges 558 engage the partially curled up strip along margins 70 and 72, as best seen in FIG. 26, to maintain the strip laterally centered at a point about midway through the punching die progression of station No. 5. Further centering of the strip is provided by the side surfaces of the lips 540 and 550 of strippers 522 and 524 which engage margins 70 and 72 as the same are leaving the last punch area of station No. 5. Also, rib 596 and guide walls 590 and 592 of the exit guide block 580-582 also assist in maintaining the strip

accurately centered and properly oriented in the punches of station No. 5.

Due to the vertical movement of paddle 496 with stripper 472, the bottom wall of the guideway through most of station No. 5 is able to track the vertical motion of stripper 246 and pressure finger 368 of station No. 4 so that flexing of the strip is minimized. Likewise, the vertical clearance provided in the exit guideway in block 580-582 allows strip 170 to move between the solid and dotted line positions thereof shown in FIG. 14 to track the vertical motion of the strip as it is being worked in station No. 5, thus reducing flexing as it leaves this station. Nevertheless, while the strip is being advanced it still is confined with relatively small clearances vertically as well as laterally because the guideway is made smaller in its vertical dimension in response to opening motion of the die set 144. Hence during the critical period that the strip is placed under compression by the pushing action of the strip feeder 154 the strip is restrained from buckling. At the same time the strip is slidably supported clear of the lower dies. Therefore legs 76 and 78 are lifted clear of the die horns by the opening movement of the die set and the corresponding upward movement of stripper 472 preparatory to each advance of the strip. Then on the next down stroke, legs 76 and 78, which are progressively lowered from their upright to their mutually crossed relationship, drop into the space provided between the next successive pairs of die horns associated with the last three punches H, I and J. This interdigital posture of the legs 76 and 78 relative to the die horns 454'-468' is best seen in the phantom view of strip 170 in FIG. 16.

Station No. 6

After strip 170 has been blanked, notched, the feet, legs and struts bent, and the strip curled to channel shape in stations Nos. 1-5 inclusive, it advances through the induction heater 600 of station No. 6 shown in FIGS. 1, 23 and 29. This heater may be the same as that disclosed in the aforementioned Burns et al. U.S. Pat. No. 2,925,847 and therefore the same is not described in detail herein. Heater 600 heats strip 170 to a temperature sufficient to relieve the stress in strip 170 caused by the previous punching and cold forming operations.

STATION NO. 7

In station No. 7, the now-channel-shaped strip 170 is progressively coiled into 706 circuit ring-shape of spacer-expander 58 and, once so coiled, the length of coil stock forming one spacer-expander is cut off from strip 170 by severing the median strip 192 in the trailing joint area 186. These operations are performed by the coil and cut-off die assembly 146 and associated operating mechanism 700 shown in FIGS. 29-36 inclusive. Referring first to FIGS. 29 and 30, the coiling anvil and shoe mechanism will be described first, followed by the description of the cut-off punch and die mechanism. The channel-shaped strip stock 170 leaving the exit end of the induction heater 600 (FIG. 29) immediately enters an entrance guide block 702 mounted on a support 704 of the framework of mechanism 700. Block 702 has a horizontal groove 76 (FIG. 31) closed at its upper end by a cover 708 which has a rib 710 dependent therefrom centrally of groove 706 to fit closely between the marginal bands 70 and 72 of strip 170 to

thereby guide the strip to a superposed guide block 712 (FIG. 30) also stationarily supported on the framework of mechanism 700. Block 712 has a pair of parallel grooves 714 and 716 in the flat undersurface thereof which are aligned with and receive therein bands 70 and 72 of strip 170, as indicated in phantom in FIG. 33. The bottom wall of groove 706 terminates at the leading end of a tungsten carbide die 718 (FIG. 30), the leading upper surface 838 (FIG. 35) of die 718 being positioned flush with or slightly above the bottom wall of groove 706 to insure that strip 170 is held with a close sliding clearance in guide block 712 immediately adjacent the cut-off punch and die set. Strip 170 feeds from block 712 to and beneath a sector-shaped tungsten carbide forming anvil 720 mounted in a holder 722 stationarily fixed to the framework of mechanism 700. Anvil 720 also has a pair of spaced grooves 724 and 726 formed in its undersurface (see FIG. 32) which form extensions of grooves 714 and 716 respectively and thus receive therein the margins 70 and 72 of strip 170. Anvil 720 is detachably mounted on support 722, as is guide block 712 so that different sizes of these parts can be mounted to accommodate different diameter spacer-expanders being formed on the machine 100. For example, anvil 720 will have a radius of curvature ranging from 0.908 inch to 1.043 inches for spacer-expanders produced in a diametrical range of, for example, 3 1/2 to 4 1/2 inches to fit in piston ring grooves of three-sixteenth inch axial dimension. The circumferential length of the curved portion of the undersurface of anvil 720 thus will be about 1 1/8 inches for spacer-expanders in the aforementioned range to thereby work in each cycle of the coiling mechanism a circumferential angular increment of about 18° each time strip 170 is advanced the aforementioned two-pitch increment by feeder 154.

The coiling curvature is imparted to strip 170 by bending what becomes the inner periphery of spacer-expander 58 against the stationary undersurface of anvil 720 with a movable coiling arm pad 728 (FIGS. 30 and 35) which slidably engages what becomes the outer periphery of the spacer-expander. Pad 35 has a smooth curved upper surface 730 concentric with the undersurface 732 of anvil 720 and is supported for pivotal movement about the axis 734 of a pivot shaft 736. The front end of shaft 736 has a cross arm 738 secured thereto which extends perpendicular to axis 734 beyond the circumference of shaft 736 and has a shoe 740 at its free end which projects forwardly in offset relation from arm 738 to provide a seat on which pad 728 is fastened. Shaft 736 is journaled by bushings 742 and 744 (FIG. 33) in a block 746 which in turn is fixedly mounted on a platform 748 which rests on a bolster 750. Bolster 750 is attached to bolster 232 of press 100 and is supported by additional legs (not shown). Platform 748 is mounted for sliding movement on bolster 750 and interlocked therewith by a key 752 (FIG. 33). The position of platform 748 on bolster 750 may be adjusted by turning an adjustment knob 754 of a lead screw 756 which extends through a threaded stationary support 758 fixedly mounted on bolster 750, screw 756 abutting at its free end against block 746. Platform 748 may be locked in adjusted position by studs 760 and 762 (FIG. 30) threaded into bolster 750.

Coiling pad 728 is pivoted from a lowered, open position shown in solid lines in FIG. 35 to a closed, forming position shown in dot-dash lines in FIG. 35 (and in solid

lines in FIG. 30) by rocking shaft 736 in synchronism with the operation of press 100. This is accomplished in the following manner. The rear end of shaft 736 (FIG. 33) has a lever arm 764 secured thereto by a nut 766 which threads onto a threaded extension 768 of shaft 736. Arm 764 extends toward station No. 6 to a free end 770 (FIGS. 30 and 35) where a cam follower roller 772 is rotatably supported on a right angle extension 774 secured to free end 770 (FIG. 33). Roller 772 tracks against the underside of a lever arm 776 adjacent the free end 778 thereof, arm 776 being pivotally mounted on a horizontal pin 780 at the upper end of a bracket 782 mounted on platform 748.

Lever arm 776 is actuated by a roller 784 (FIGS. 30, 35 and 36) carried on a pin 786 secured to the lower end of a tongue 788 which is dependent from a slide block 790 mounted for vertical adjustment in a guide-way of a carrier block 792. An adjustment screw 794 is journaled in a plate 796 secured to the upper end of block 792 and is threaded into a threaded bore in carrier 790 to adjust the vertical position of roller 784. Carrier block 790 in turn is mounted on the rear side of an actuator plate 798. Plate 798 is mounted for vertical reciprocating movement in synchronism with ram 130 and is guided on a pair of guide posts 800 and 802 (FIGS. 30 and 33) mounted in block 746. The rigid connection of plate 798 with ram 130 is through an arm 804 bolted at one end to the underside of ram 130 and extending from behind station No. 6 toward station No. 7, as best seen in FIGS. 29 and 30, to a free end 806 connected to plate 798 by gibs 808 and 810.

The operation of coiling pad 728 with respect to stationary anvil 720 thus is accomplished through the motion of the press ram 130. On the down stroke of ram 130, plate 798 will be forced downwardly by arm 804 from its raised position shown in FIG. 35, wherein roller 784 is poised spaced above its point of contact with lever 776, to a lowered position as shown in FIG. 30 corresponding to the closed die position of press 100. When roller 74 strikes arm 776 on its down stroke, arm 776 is pivoted downwardly in a counterclockwise direction, thereby pivoting arm 764 in the same direction and imparting like rotation to shaft 736, thereby rocking pad 728 from its open position shown in FIG. 35 upwardly to its closed position shown in dot-dash lines in FIG. 35. This curls the strip from the phantom position A to phantom position B as shown in FIG. 35.

When ram 130 is lifted on its up stroke, roller 784 likewise is lifted clear of contact with lever arm 776 when shoe 740 is fully opened and thus bottomed against a stop (not shown) on holder 830. However, since the weight of arm 776 and arm 764 will tend to maintain pad 728 in the closed position, a coil wire spring (not shown) is connected to free end 770 and extends upwardly to a connection with a stationary part of mechanism 700 to bias levers 764 and 776 upwardly to their positions shown in FIG. 35, thereby biasing pad 728 downwardly to its open position. Strip 170 is then advanced by another two-pitch length increment as illustrated in FIG. 35, thereby feeding strip 170 and the coiled portion thereof to the right as viewed in FIG. 35 to the right-hand phantom position A shown in FIG. 35.

The circumferential length of the portion of strip 170 worked in each stroke of pad 178 is two pitch lengths for each feeding increment. Hence each two-pitch increment will be struck about twice between pad 728 and anvil 720 as it traverses the same. As best illus-

trated in FIG. 35, strip 170 will curl up into a full circle above the coiling dies. In order to support and stabilize the strip as it is being coiled up to the full circle condition, a ring guide plate 812 is provided which is shown in full in FIG. 29 and fragmentarily in FIG. 35 but which has been removed from the illustration in FIG. 30 in order to better show the structure behind the plate 812.

Referring to FIG. 29, plate 812 is stationary and extends vertically in a plane parallel to the direction of strip feed. The plate is generally centered on the coiled position of the strip as it leaves the anvil 720, and it has a horizontal dimension in the direction of strip feed about twice the diameter of a coiled spacer-expander 58. Plate 812 has a cut-out edge 814 (FIG. 35) which is disposed adjacent the path of travel of the outer tip of pad 728, and has a bent lip 816, the leading edge 818 of which is disposed slightly rearwardly of the path of travel of the strip 170 as it leaves the coiling anvil. Lip 816 extends generally radially of and beyond the position of the coiled strip 170 both after it has been advanced with pad 728 open and also after it has been curled upon closure of pad 728. Lip 816 fairs into the main surface of plate 812 at the line indicated 820 in FIG. 35, this main surface 822 being disposed flush with the rearward side of strip 170 when disposed in anvil 720. Hence the strip 170 will lie closely adjacent or against plate 812 as it curls up to the full circle position prior to the same being cut off by the punch and die set of station No. 7.

When the full length of a spacer-expander has been coiled up into a circle at station No. 7 as described above, and the trailing joint area 186 has become into registry with the cut-off punch and die set of station No. 7, the coiled spacer-expander is severed from the uncoiled strip trailing it by severing the median strip 192 midway between the cross arms 281 shown in FIGS. 4 and 34. The cut-off punch and die structure is best seen in FIGS. 30, 33 and 35. The stationary structure of the die set comprises a die holder 830 mounted on block 746 by clamp 832 and adjustable in the direction of strip feed thereon by a pair of screws 834 and 836 (FIG. 30). Holder 830 supports at its upper end the aforementioned cut-off die 718 which has a flat horizontal surface 838 flush with and forming a continuation of the bottom wall of groove 706 in block 702. Surface 838 terminates in advance of a rectangular hole 840 in die 718, the remaining surface 839 of the upper end of die 718 in the vicinity of hole 840 and downstream therefrom also being flat and horizontal but about 0.002 inch lower in elevation than surface 838. Hole 840 communicates with a scrap passageway 842 in holder 830 which in turn communicates with the scrap removal passages in base 746, platform 748 and bolster 750.

The movable structure of the cut-off die set includes a cut-off punch 850 supported in a punch holder 852 which in turn is fastened by a stud 854 (FIG. 33) to the underside of the front edge of a cut-off actuator plate 856. Stud 854 also serves to mount a wear button 858 on plate 856. Plate 856 in turn is slidably mounted for vertical reciprocatory movement by a pair of bushings 860 and 862 (FIG. 30) which are slidably guided on the upright posts 800 and 802. A pair of compression coil springs 864 and 866 encircle posts 800 and 802 respectively between base 746 and bushings 860 and 862 to bias plate 856 to a raised position as determined by the

abutment thereof with the heads of a pair of stop studs 868 and 870 mounted on base 746.

Punch 850 is reciprocated vertically from the raised position thereof shown in FIGS. 30 and 33 to its lowermost position, wherein the nose of the punch enters the cut-off hole 840 of die 718, by utilizing the motion of plate 798. An air cylinder 870 (FIG. 33) is mounted by a bracket 872 to the rear of plate 798 and has a plunger 874 which carries a block 876 at its free end which slides against the horizontal undersurface 878 of plate 798 between the retracted and extended positions shown in solid and dotted lines respectively in FIG. 33. Air cylinder 870 is connected by a pressure line 880 to a source of compressed air under the control of a solenoid valve actuated by the aforementioned counter control mechanism to cause shoe 876 to be extended to the dotted-line position in synchronism with the registry of the mid point of strip 192 over the die hole 840. This is accomplished by the digital memory counting and storing the number of signals from unit 160 corresponding to the number of cycles of press 100 required to advance one spacer-expander length through the coiling anvil of station No. 7. The control mechanism then produces an actuating signal for the solenoid valve which controls cylinder 870 in response to the count total corresponding to registry of strip 192 with die 838.

With shoe 876 thus extended, on the next stroke of the press, plate 798 in moving down with the ram 130 will carry the outer end of shoe 876 into abutment with button 858, whereupon actuator plate 856 and punch 85C carried thereon will be driven downwardly through the working stroke of the punch. On the up stroke of the press, upward movement of shoe 876 will allow the springs 864 and 866 to raise plate 856 to its upper limit of its travel shown in FIGS. 30 and 33. Shoe 876 will thereafter continue moving up with plate 798 until it reaches its uppermost position shown in FIG. 33. Then air cylinder 870 is actuated to retract shoe 876 to its retracted position where the forward end of the shoe will clear button 858 on the next downstroke of the press, as indicated in FIG. 30. Punch 850 thus operates to sever strip 192 and remove a small portion of the strip between tabs 281 of two successive spacer-expander lengths, as shown in FIG. 34.

Once the coiled spacer-expander has been thus severed from the trailing strip 170 in station No. 7, it will drop clear of the grooves 732 in anvil 720 when pad 728 is opened in response to the up stroke of the press, this action occurring as punch 850 is rising.

It is to be noted that surface 838 maintains the margins 70 and 72 of the strip in the grooves of anvil 720 so long as strip 170 is continuous and extends from guide 702 over die 718 and under anvil 720; i.e., until such time as the joint area 186 comes into registry with the die 718. It also is to be noted that die holder 830 has a trailing rib 831 carrying a narrow trailing portion 179 of die 718 to form a narrow trailing extension of surface 839 (FIG. 35). Pad 728 is provided with a narrow slot 729 (FIG. 35) near its leading edge which receives rib 831 and die 719, as best seen by comparing FIG. 35 to FIG. 30. The upper surface of die 719 thus provides a bridge between die 718 which leads into the upper surface 730 of pad 728 to provide a smooth transition to carry the strut 74 of the strip onto surface 730 during strip advance. When the coiled strip 170 has been severed, the leading end 880 (FIG. 35) of the

semi-finished spacer-expander 58 will have traveled through the circular path adjacent the front surface of guide plate 812 and will have reached the position shown in FIGS. 29 and 35. Leading end 880 thus will have come into sliding contact with the downwardly and forwardly inclined surface of an apron 882 (FIGS. 29 and 35). Apron 882 is attached to the lower edge 884 of the front half of surface 822 of plate 812 and extends at its right-hand end over to a point just short of the cut-off punch and die of station No. 7. The lower right-hand corner of apron 882 rests on a flange 886 of a stringer transfer guide 883 (FIG. 29). Guide 888 also comprises a continuous hollow tube 890 of about half the diameter of a spacer-expander 58 which has a nose cone 892 with its point 894 approximately flush with the surface 822 of plate 812 and generally centered on the center of the fully coiled but unsevered spacer-expander when positioned for the cut-off stroke of punch 850. Guide 888 extends horizontally outwardly from the cone 892 and then has a smooth, curved transition to an inclined portion 896 which is inclined outwardly and downwardly away from station No. 7. Portion 896 in turn has a smooth curved transition to a vertical section 898 of tube 890. The underside of tube 890 has a vertical fin 900 secured thereto which leads all the way from the tip 894 of the nose cone downwardly to station No. 8, as shown in FIG. 1. The flange 886 extends horizontally from both sides of the lower edge of fin 900 and generally follows the path of tube 890 downwardly to station No. 8. The distance from the outer upper surface of tube 890 diametrically of the tube and through fin 900 to flange 886 is slightly greater than the diameter of the coiled spacer-expander 58.

Station No. 7 also has a semi-circular air tube 902 which is closed at its ends and arranged as shown in FIG. 29 to embrace the upper half of a coiled spacer-expander when the same is substantially completely coiled and disposed against surface 822 of plate 812. Compressed air is applied to tube 902 by a conduit 904 connected to the tube midway between its ends. Tube 902 has a series of small holes 906 facing radially inwardly of tube 902 to thereby direct a plurality of air jets, as indicated by the arrows 908 in FIG. 29, along the surface of plate 822 and toward the coiled-up spacer-expander to thereby blow the same axially away from surface 822 and onto the stringer guide 888. This action occurs in synchronism with the release of the ring in response to retraction of coiling pad 728 so that as soon as the coiled-up spacer-expander has been severed from the strip 170 and released, it will be blown immediately onto guide 888.

It will be noted that at this point in the cycle, disposed to the left of fin 900, as viewed in FIG. 29, while the trailing end which has just been severed from the strip 170 will be disposed on the right-hand side of fin 900. Hence when the severed spacer-expander 58 is blown away from plate 812 and drops by gravity onto the upper surface of tube 890, the leading and trailing ends of the spacer-expander will be at opposite sides of fin 900. Hence the spacer-expander is properly angularly oriented to clear fin 900 and, due to fin 900 being interposed in the gap between the parted ends of the spacer-expander, fin 900 will maintain this orientation as the spacer-expander slides downwardly along guide 888 onto the nose cone 910 of station No. 8. The diameter of tube 890 is sufficiently large to prevent the spac-

er-expander 58 from pulling loose from stringer 888 during its descent thereon to station No. 8. It is also to be understood that spacer-expander 58 is curled by die assembly 146 to a diameter which imparts a negative gap, i.e., the parted ends tend to overlap in the free-state condition of spacer-expander 58. This also helps retain the ring segment 58 on tube 890.

STATION NO. 8: STRINGER GUIDE

In station No. 8 the coiled spacer-expander 58 is 10 worked to complete the formation of the two end joint tabs 275 in a joint trimming and bending operation which converts the joint stock from that shown in FIG. 47 to that shown in FIG. 53. The structure of station No. 8 is supported on a framework comprising a backbone column 920 (FIG. 39) having a top plate 922 secured to the bolster 750 of the press framework 102 (FIG. 1). Column 920 extends downwardly to and supports a lower framework 924. Station No. 8 has a cylindrical, vertically extending guide 926 supported at its rear by frame 920. The stringer guide tube 888 is joined at its lower end to the upper end of a frustro-conical nose cone 910, which is generally the same diameter at its upper end as tube 888. Cone 910 diverges outwardly and downwardly to the diameter of guide 926 and is joined at its lower end to guide 926. As best seen in FIG. 44, guide 926 is hollow and has a cylindrical upper portion 928 large enough to spread apart the gaps and roughly space them to final positioning at the work station. As the parted ends approach the work station, they strike the downwardly and outwardly diverging surfaces of an inverted V-shaped guide 928' (FIGS. 39 and 44). Guide 928' is mounted upright on guide 926 above the upper end of block 1072 and terminates at its lower end just above surface 930. Guide 928' serves to further spread apart the parted ends as the spacer-expander is pushed downwardly so they will be positioned adjacent and outwardly of the horns 1118 and 1120 when spacer-expander 58 drops from surface 928 onto shelves 1020 and 1020' and thus comes to rest adjacent surface 930. Guide 926 also has an undercut cylindrical surface 930 coinciding with the trim and bending work area of station No. 8, which has a diameter related to the inside diameter of the spacer-expander to assist in properly positioning the same as explained in more detail subsequently herein. Below surface 930 there is an outwardly flaring conical shoulder 932 which leads to a larger diameter lower cylindrical portion 934 of guide 926. Portion 934 is sufficiently large in diameter to expand spacer-expander 58 and, with guide 1072' described subsequently, spread apart its parted ends so they clear the supporting structure and mechanism which enter guide 926 from the rear thereof.

In order to accommodate different sizes of spacer-expanders, guide 926 is provided with a vertically extending slot in the outer surface thereof diametrically opposite fin 900. An expander strip 936 is mounted in this slot for horizontal adjustment on a pair of guide pins 938 and 940 (FIG. 37) controlled by a pair of adjusting screws 942 and 944 which thread into the inset back wall 946 (FIG. 44) of the slot of guide 926. Expander 936 extends from the upper end of nose cone 910 downwardly to the lower end of guide 926 and has a profile in vertical section which matches that of guide 926, as best seen in FIG. 44. A series of such expanders 936 is provided, each having the same profile but with

different thicknesses, and a suitable size expander is selected for installation on guide 926. Thus, by selecting the proper expander 936 and then making the proper fine horizontal adjustment (radially of guide 926), the effective inside diameter of guide 926 can be varied to suit that of the particular size spacer-expander 58 being made on machine 100.

STATION NO. 8: TRANSFER PUSHER ASSEMBLY

Referring to FIGS. 37, 38, 39 and 41, spacer-expanders 58 are advanced through station No. 8 by two horizontally and vertically movable pushers 946 and 948 disposed generally for sliding engagement with and along the left and right-hand sides of cone 910 and guide 926 as viewed in FIG. 37. Left-hand pusher 946 has a side wall 950 which is a segment of a cylinder having a radius matching that of portion 934 of guide 926 and extending through an angle of about 120°. A horizontal flange 952 is secured to the lower edge of wall 950 and extends radially outwardly therefrom to provide a flat pushing surface for pushing a spacer-expander down cone 910 and guide 926. A plate 954 is secured to the upper edge of wall 950 and extends radially outwardly therefrom to a pin 956 by which pusher 946 is pivotally mounted on the free end of a swinging arm 958. The angular orientation of pusher 946 relative to arm 958 is adjustable by a threaded stop screw 960 carried on a bracket 962 fixed to the outer end of arm 958. Arm 958 has an outer section 964 and an inner section 966 connected by a link 968 to permit lengthwise adjustment of arm 958. Inner arm section 966 is mounted on the upper end of a vertical shaft 970 for rotation therewith. Similarly, right-hand pusher 948 is mounted on an extendable swinging arm 972 supported on the upper end of a vertical shaft 974 and is identical to pusher 946 but of opposite hand construction. Shafts 970 and 974 are journaled for rotation in and vertically slidably through bearing sleeves 976 and 978 respectively (FIG. 37) secured to framework 920. The lower ends of shafts 970 and 974 project downwardly from sleeves 976 and 978 into a bridge plate 980 which vertically supports the shafts on bearing seats therein (not shown). Reduced diameter extensions of shafts 970 and 974 project below bridge 980 and have respectively secured thereto finger clamps 982 and 984 (FIGS. 37 and 41) which are yieldably drawn toward one another by a tension coil spring 986 secured at its ends to pins 988 and 990 fastened to fingers 982 and 984 respectively. Thus, spring 986 through shafts 970 and 974 tends to swing pushers 946 and 948 toward one another into sliding embracing relationship with cone 910 and guide 926.

Bridge 980 is supported for vertical movement on the upper end of a plunger or piston rod 992 of an air cylinder 994 mounted at its upper end by a bracket 996 to frame 920 (FIG. 39). Plunger 992 extends all the way through cylinder 994 and has a head 998 to its lower end adapted to abut the upper end of a plunger 1000 of an air cylinder 1002 stationarily mounted on the lower end of frame 924. When cylinder 994 is actuated to lift shaft 992 to the uppermost position thereof shown in FIG. 39, shafts 970 and 974 likewise will be lifted to their raised position shown in FIGS. 37 and 39 to elevate pushers 946 and 948 to their uppermost positions shown in FIG. 37. In this position, the rear ends of the inner sections 966 and 973 of arms 958 and 972 respectively are disposed in alignment with the heads

1004 and 1006 of the plungers 1008 and 1010 of air cylinders 1012 and 1014 respectively. These cylinders are stationarily mounted by brackets 1016 and 1018 to the sides of frame 920. In the retracted position of plungers 1008 and 1010, their respective heads are withdrawn outwardly and clear of the outermost swing-apart positions of arm extensions 966 and 973; i.e., when the arms 958 and 972 are pulled by spring 986 into parallel relationship to swing pushers 946 and 948 inwardly against cone 910, as shown in FIG. 38 and in phantom in FIG. 41.

Station No. 8: Supporting Shelves and Positioning Fingers

Referring to FIGS. 37, 38, 39, 42 and 46, a spacer-expander 58 is vertically supported at the work station of station No. 8 by a pair of horizontally movable shelves 1020 and 1020' arranged diametrically opposite one another on the left and right-hand sides of guide 926 respectively as viewed in FIGS. 37 and 42. The opposite side edges of left-hand shelf 1020 are slidably supported in the ways of a pair of guide blocks 1024 and 1026 of a plate bracket which is secured to a framework 1028 mounted to one side of frame 920 (FIG. 42). Right-hand shelf 1020' is similar to shelf 1020 and likewise is supported by corresponding structure to the right side of frame 920. Shelf 1020 is reciprocated between its retracted position shown in solid lines in FIG. 42 and its extended position shown in phantom in FIG. 42 by an air cylinder 1030 (FIG. 37). Cylinder 1030 is pivotally supported at its lower end on a pin 1032 supported on the lower end of a hanger bracket 1034 of framework 1028. Cylinder 1030 has a vertically reciprocable plunger 1036 protruding from its upper end pivotally connected to one arm of a bell crank 1038 pivotally mounted on hanger 1034, the other arm of crank 1038 being connected to a finger 1040 dependent from the underside of shelf 1020 and extending through a slot in guide plate 1027. A corresponding air cylinder 1030' and like structure vertically reciprocates shelf 1020' between the solid-line and broken-line positions thereof shown in FIG. 42. The inner edges 1042 and 1042' of shelves 1020 and 1020' respectively are shaped to match the curvature of the conical shoulder 932 of guide 926 and abut the same as shown in FIG. 38 when the shelves are in their extended position embracing guide 926. The flat, horizontal upper surfaces 1044 and 1044' of shelves 1020 and 1020' thus are located flush with the lower edge of the cylindrical portion 930 of guide 926 to thereby form a stationary platform on which the spacer-expander rests to thus vertically locate the same in registry with the joint trimming and bending dies described hereinafter. When shelves 1020 and 1020' are retracted to the solid-line positions thereof shown in FIG. 42, there is sufficient clearance between edges 1042 and 1042' and guide 926 to permit pushers 946 and 948 and their associated flanges 952 and 952' to pass vertically downwardly past the shelves to the lowermost position of the pushers shown in broken lines in FIG. 38, thus allowing the pushers to push a spacer-expander out of the work station of station No. 8 and downwardly along surface 934 of guide 926 after completion of the joint trimming and bending operation.

Once a spacer-expander has landed on the closed shelves 1020 and 1020', it is gripped by a pair of positioning fingers 1044 and 1044' carried respectively on

shelves 1020 and 1020', as best seen in FIG. 42. Referring to left-hand finger 1044, a bracket 1046 is secured adjustably to the upper surface of shelf 1020 at the outer end thereof to support an air cylinder 1048. The plunger 1050 of cylinder 1048 extends horizontally toward guide 926 and carries a head 1052 which slides on shelf surface 1044 and is undercut to receive an outer portion of finger 1044 therein. Finger 1044 is mounted pivotally on head 1052 by a pin 1054 and also slides on shelf surface 1044. A tension coil spring 1056 is connected at one end to a pin 1058 secured to shelf 1020 and at the other end to a lug 1060 secured to finger 1044 to thereby bias the finger yieldably to the position shown in solid lines in FIG. 42 wherein the outer corner 1062 of the finger 1044 abuts the back wall of the undercut in head 1052. In this position of finger 1044, its curved inner edge 1064 is canted so that the rounder nose 1066 of finger 1044 leads its inner edge 1064 into engaging relation with the outer periphery of the spacer-expander when finger 1044 is shifted from its retracted toward its fully extended position shown in broken lines in FIG. 42 (see also FIG. 46).

Finger 1044' likewise is mounted by corresponding structure on shelf 1020' for movement therewith as well as independently thereof through the action of its associated air cylinder 1048'.

Station No. 8: Joint Trimming and Bending Die Subassembly

30 The die and clamp parts of the punch and die assembly 148 of station No. 8 are mounted in a die holder 1068 secured to the upper end of a movable die shoe 1070 which is disposed within the hollow interior of guide 926, as best seen in FIGS. 42 and 44. Guide 926, as well as the punch, clamp and die assembly 148 of station No. 8, are carried on a framework 1071 affixed to the main frame 920, this framework including a vertical plate 1072 to which guide 926 is bolted. Plate 1072 in turn is carried on a bracket 1073 secured via a back plate 1074 to frame 920. Shoe 1070 is supported on the inner ends of a pair of vertically spaced guide posts 1076 and 1078 which extend horizontally and slidably through plate 1072 and which are connected at their outer ends to a vertical bridge 1080. 45 The outer end of a plunger 1082 of an air cylinder 1084 is connected to the center of bridge 1080 to reciprocate shoe 1070 horizontally between the broken and solid-line positions thereof shown in FIG. 44, cylinder 1084 being stationarily mounted on plate 1074.

50 Plunger 1082 extends all the way through cylinder 1084 so that its rear end 1086 protrudes therebeyond and carries a locator block 1088 which is slidably supported for horizontal movement within a guideway 1090 in a housing 1092 fixed to frame 920. As best seen in FIG. 43, block 1088 has a pair of coaxially aligned left and right-hand bushings 1094 and 1094' mounted therein to provide inwardly tapering conical sockets 1096 and 1096' in opposite sides of the block. 55 These bushings are axially aligned with a pair of conical nose shot pins 1098 and 1098' (FIG. 42) in the closed condition of punch and die assembly 148; i.e., when shoe 1070 and block 1088 have been shifted by cylinder 1084 to their position as viewed in FIG. 44. Shot pins 1098 and 1098' are mounted slidably in bushings 60 in housing 1092 (FIGS. 42 and 42) and are actuated respectively by associated air cylinders 1100 and 1100' mounted to opposite sides of housing 1092. However,

closing movement of shoe 1070 is stopped by the abutment of a stop stud 1102 (FIG. 44) threaded through shoe 1070 against a stop button 1104 mounted in plate 1072. Movement of shoe 1070 to this position brings sockets 1096, 1096' into alignment with the associated shot pins 1098 and 1098' while the same are in their retracted positions clear of the guideway 1090. Then cylinders 1100 and 1100' are actuated simultaneously to drive the shot pins into their respective sockets to thereby securely hold shoe 1070 in closed position.

The clamp and die set mounted in shoe 1070 is best seen in FIGS. 46, 49 and 52 and is also shown in FIGS. 42 and 43. This die set consists of two form dies 1106 and 1108 flanking a central shear punch and clamp 1110, all projecting horizontally and rearwardly from shoe 1070 near the upper end thereof through a passageway 1112 in guide 926 and plate 1072 (FIGS. 46 and 44). For dies 1106 and 1108 are identical but arranged back-to-back and have rectangular cross-section shanks bearing against the opposite sides of the rectangular section shank of trim punch 1110. The outer end of punch 1110 has a flat surface 1114 perpendicular to the longitudinal axis of the punch and disposed slightly outwardly of the end surface 1116 of a bending horn 1118 which projects from the end of the shank of die 1106. Bending horn 1120 of die 1108 projects flush with horn 1118.

As best seen in FIGS. 46, 47 and 52, horns 1118 and 1120 each have a vertical dimension (perpendicular to the plane of the drawing in FIG. 46) which is narrower than the spacing between the marginal bands 70 and 72 of the spacer-expander. Hence end strut 74 of the left-hand end of spacer-expander 58 can feed over and embrace horn 1118 and be accurately located with its central portion lying on the upper surface 1116 of the horn when the leg 78 adjacent the end strut 74 bears against the side surface 1122 of horn 1118 as shown in FIGS. 46 and 49. The same relationship exists between the right-hand end of spacer-expander 58 and the bending horn 1120 when the leg 76 at this end closest to the right-end strut 74' envelopes bending horn 1120, as explained more fully hereinafter.

As will be seen from comparing FIGS. 46, 48 and 49, the inner corner of the outer end of each horn 1118 and 1120 has a rounded surface to provide the proper bending radius around which the stem 277 of the associated end pad 275 is bent in bringing it to its finished position as shown in FIGS. 49 and 53. As will be seen by comparing FIGS. 46 and 47, when legs 78 and 76 of the left and right ends of spacer-expander 58 are abutting their respective horns 1118 and 1120, and the inner periphery of the spacer-expander is held against the cylindrical surface 930 of guide 926, the terminal ends 192a and 192b which extend from the cross arms 281 of the end joints lie on surface 1114 of punch 1110 and the outer edges of the cross arms 281 of tabs 275 are aligned with the opposite side surfaces of punch 1110. As will be best seen in FIG. 52, the side edges of the leading surface 1122' of horn 1120 are beveled to assist in camming the end edges of the marginal bands 70 and 72 around the horn as spacer-expander 58 is brought into position at the work station of station No. 8 by the choking action of fingers 1044 and 1044' as described subsequently. The same profile but in reverse exists on horn 1118.

Station No. 8: Joint Trimming and Forming Punch Subassembly

Referring to FIGS. 42, 44 and 46, the trimming and bending punches of punch and die assembly 148 are combined with a series of clamps which are horizontally movable from the open position thereof shown in FIG. 42 to the closed positions thereof shown in FIGS. 44 and 49. The punch subassembly is supported on a platform 1130 (FIGS. 39, 42 and 44) which is secured to frame 920. Platform 1130 has four upright corner posts 1132, 1134, 1136 and 1138 in which are stationarily mounted a pair of horizontal guide posts 1140 and 1142 which slidably support for horizontal movement a punch shoe 1144 and a clamp shoe 1146. Shoe 1144 carries a punch holder subassembly 1148 in which are mounted a pair of cut-off and form punches 1150 and 1150' disposed in horizontally spaced-apart relationship and project from the front of holder 1148 horizontally through associated guideways in clamp shoe 1146. Shoe 1146 has a clamp holder 1152 which retains in fixed position in shoe 1146 a pair of side clamps 1154 and 1154', the ends of which protrude horizontally from the front face of shoe 1146. Shoe 1146 has formed integrally therewith a center clamp 1156 which extends the full width of the shoe and protrudes horizontally from the front face thereof in slightly recessed relationship to the front faces of clamps 1154 and 1154'. The punches 1150 and 1150' thus extend on either side of clamp 1156 and in turn are flanked respectively by clamps 1154 and 1154'. Thus, the clamps and holder of shoe 1146 define guideways through which punches 1150 and 1150' can slide.

Shoe 1146 has a lost-motion connection with shoe 1144 by means of a pair of bolts 1158 and 1158' which are threaded into shoe 1146 and extend slidably through shoe 1144. A pair of compression coil springs 1160 and 1160' respectively encircle bolts 1158 and 1158' and abut at their front ends against the rear surface of shoe 1146 and at their rear ends against the end wall of counterbores in shoe 1144. Thus, the springs bias the shoes apart to the position shown in FIG. 42 wherein shoe 1144 is shown abutted against heads of bolts 1158 and 1158'. Shoes 1144 and 1146 are reciprocated horizontally by an air cylinder 1164 (FIGS. 39 and 44) which is mounted on the rear of housing 1092, the plunger 1166 of cylinder 1164 being secured to the rear side of shoe 1144 and extending through an opening in housing 1092.

As best seen in the enlarged views of FIGS. 46, 48, 49, 50 and 51, the leading end of clamp 1156 has a flat face perpendicular to the direction of travel of the punch which registers with face 1114 of clamp 1110 to clamp the terminal portions 192a and 192b therebetween when shoe 1146 is driven forwardly by the forward motion of shoe 1144. Simultaneously therewith, clamps 1154 and 1154' clamp the center portions of the end struts 74 and 74' at the left and right ends respectively of spacer-expander 58 against the end surface 1116 of horns 1118, 1120 as shown in FIG. 46. This clamping action halts further forward motion of the shoe 1146, but shoe 1144 continues to move horizontally and forwardly against the pressure of springs 1160 and 1160' to thereby cause punches 1150 and 1150' to move through shoe 1146 and relative to its clamps 1154 and 1154' from the position shown in FIG. 46 to the almost fully extended position shown in

FIG. 49. As best seen in FIG. 48, when the leading ends of punches 1150 and 1150' strike cross arms 281 and 281' respectively, the same are sheared from the clamp terminal portions 192a and 192b respectively. Immediately following the shearing action, the bending surfaces of the punches strike the stems 277 and 277' and carry them forward to bend the same around the bending radii of horns 1118 and 1120 and then forces them against the inner surfaces of the horns, with a sliding clearance between surfaces 1151 and 1151' and stems 277 and 277' respectively, as the punches reach their almost fully extended position in FIG. 49.

It is to be noted that punches 1150 and 1150' each have a pair of ears 1160 and 1162 (FIG. 51) at their outer edges bounding the central bending surfaces 1164, the ears being spaced laterally apart a distance sufficient to pass downwardly alongside the outer edges of the cross arm 281 of the end 275 of the spacer-expander. Also, surface 1164 is slightly inclined rearwardly and outwardly from its shearing edge adjacent clamp 1156 to insure that the shearing action occurs prior to the bending action. Similarly, clamps 1154 and 1154', as shown in FIG. 50, each have ears 1166 and 1168 and a recessed central portion 1170 dimensioned so that the ears straddle the central portion of strut 74 and help center the same on horn 1118 as the clamp approaches its final clamping position shown in FIG. 46.

Punches 1150 and 1150' also have flat surfaces 1153 and 1153' respectively which are inclined rearwardly from surfaces 1151 and 1151' respectively (FIG. 48) and extend outwardly to the adjacent side surfaces of the adjacent clamps 1154 and 1154'. As punches 1150 and 1150' reach their fully extended positions on the closing stroke of shoe 1144, surfaces 1153 and 1153' strike the bends in stems 277 and 277', coining them to the flat angle of surfaces 1153 and 1153'. This sets the crossbars 281 and 281' against the associated ends of bands 70 and 72 and reduces or eliminates spring back of stems 277 and 277' upon withdrawal of punches 1150 and 1150'.

OPERATION OF STATION NO. 8

At the beginning of a cycle of operation of station No. 8, pushers 946 and 948 are in their uppermost position and are maintained spread apart by actuating air cylinders 1012 and 1014 to the position thereof shown in FIG. 41. At this time, shelves 1020 and 1022 have been closed against surface 932 of guide 926 by their associated cylinders 1030 and 1030', but fingers 1044 and 1044' are in their retracted position relative to the associated shelf as shown in FIG. 42. The die shoe 1070 and associated punch shoe 1144 and clamp shoe 1146 are also retracted to the open condition of punch and die assembly 148 as shown in FIG. 42, shot pins 1098 and 1098' likewise being retracted at this time. The plunger 1000 of air cylinder 1002 is raised to its uppermost position shown in solid lines in FIG. 39 to provide a stop for limiting downward travel of plunger 992 of air cylinder 994 so that pushers 946 and 948 are limited in downward travel to the distance identified A in FIG. 38.

With the parts positioned as indicated above, assume that a spacer-expander 58 has just been ejected from station No. 7 and has slid down stringer tube 888 and then landed on the nose cone 910 of station No. 8. The resilient, parted spacer-expander will be expanded by

cone 910 until its resistance to such expansion causes it to frictionally cling to the cone about two-thirds of the way down the same, which is an elevation below that of the lower flanges 952 and 952' of pushers 946 and 948 when in their uppermost position of FIG. 37. The start of the operating cycle of station No. 8 is then initiated by the aforementioned digital counter control which is set to provide an actuating signal for the solenoid valves (not shown) controlling retraction of the 10 plungers of air cylinders 1012 and 1014 after a predetermined time interval from the initiation of the ejection air blast at station No. 7. This interval is sufficient to allow the spacer-expander to come to rest on cone 910.

When cylinders 1012 and 1014 are thus actuated to retract their plungers 1008 and 1010, spring 986 pulls pushers 946 and 948 together into clamping relation with cone 910 as shown in FIG. 38. This movement of arms 958 and 972 actuates a microswitch (not shown) 20 which is connected to the control valve for cylinder 994 to thereby cause plunger 992 to descend until its lower end 998 strikes the upper end of plunger 1000. This, in turn, lowers pushers 946 and 948 so they slide downwardly along cone 910, pushing the spacer-expander ahead of them. The cone cams the fingers 25 apart against the yieldable resistance of spring 986 until the lower ends of the pushers reach the cylindrical surface 928 of guide 926. The fingers then remain at the diameter of this surface as they continue their sliding descent through the distance A shown in FIG. 38 to thereby push the spacer-expander onto the upper surfaces of shelves 1020 and 1020' and in registry with guide surface 930. When head 998 strikes plunger 1000, the undersides of pusher flanges 952 and 952' are spaced with a very slight clearance above the upper side of the spacer-expander when the same is resting on shelves 1020 and 1022. Due to the reduced diameter of the undercut surface 930 of guide 926, the spacer-expander will tend to drop onto the shelves as soon as it is pushed past the larger diameter surface 928.

The motion of the bridge 980 with plunger 992 in bringing pushers 946 and 948 to the lower limit of distance A actuates another microswitch (not shown) 45 which operates the control valve for cylinder 1084 to actuate the cylinder to move shoe 1070 from its open position shown in FIG. 42 (also shown in broken lines in FIG. 44) to its closed position shown in solid lines in FIGS. 44 and 46. This motion trips still another microswitch which controls the valve for cylinders 1100 and 1100' to thereby cause the cylinders to move their associated plungers toward one another to engage shot pins 1098 and 1098' in the associated sockets 1096 and 1096' in block 1088 to thereby lock shoe 1070 in its closed position so that it is adequately supported to resist the forming pressure of the joint trimming and bending punches.

The next motion, which is initiated by a microswitch 60 (not shown) tripped in response to the completion of the engagement of the shot pins, is the actuation of cylinders 1048 and 1048' to drive the positioning fingers 1044 and 1044' toward one another. Due to the canted position of these fingers imparted by springs 1056 and 1056', the rounded noses 1066 and 1066' will be the first portion of the finger to engage the outer periphery 65 of the spacer-expander, and will do so at about 20° from the parted ends of the spacer-expander. As fingers 1044 and 1044' continue to close about the outer pe-

periphery of the spacer-expander, they will pivot about the axis of pins 1054 and 1054', causing the noses 1066 and 1066' to move circumferentially of the spacer-expander toward one another while, at the same time, developing a squeeze pressure on the spacer-expander, the combined effect of which is to choke and thus contract the spacer-expander to bring its parted ends toward one another. Due to the pre-set positioning of guide expander 936, the terminal portions 192a and 192b of the spacer-expander cannot close to a point where they would overlap or touch one another. Instead, the ends of the spacer-expander will be moved with a combined motion circumferentially toward one another and radially inwardly toward surface 930 during the final closing motion of fingers 1044 and 1044'. This brings the end struts 74 and 74' onto horns 1118 and 1120 and moves them toward one another until the edge of the adjacent end legs 78 and 76 strike the outer vertical surfaces 1122 and 1122' of horns 1118 and 1120 as shown in FIG. 46. At the same time, the inner periphery of margins 70 and 72 in the vicinity of the ends of spacer-expander 58 will be bottomed against surface 930. This final closing motion against the horns thus locates the portions 192a and 192b so as to overlie the end surface 1114 of clamp 1110 (FIG. 46).

When blocks 1052 and 1052' reach their fully extended position corresponding to the closed position of fingers 1044 and 1044' (shown in broken lines in FIG. 42), still another microswitch (not shown) is actuated which energizes the solenoid valve controlling cylinder 1164 to thereby extend the plunger 1166 thereof to move the punch shoe 1144 from its open position shown in FIG. 42 to its closed position shown in FIG. 49. As described previously, clamp shoe 1146 will be carried ahead of shoe 1144 due to the pressure of springs 1160 and 1160' so that the first action will be engagement of clamp 1156 with the end portions of the spacer-expander to thereby clamp portions 192a and 192b firmly against surface 1114 of the die clamp 1110. At the same time, clamps 1154 and 1154' firmly clamp the center portion of the struts 74 and 74' against the outer end surfaces 1116 of horns 1118 and 1120 respectively. Then, as punches 1150 and 1150' continue their forward movement with shoe 1144, they strike strip 192 and with a shearing action trim portions 192a and 192b from the end tabs 275. As punches 1150 and 1150' continue moving toward closed position, they bend and coin the stems 271 and 271' of the tabs to their final position shown in FIG. 49. This completes the formation of the spacer-expander 58.

The motion of plunger 1166 to its fully extended position trips still another microswitch (not shown) which is connected to the solenoid control valves for cylinders 1100, 1100', 1084 and 1164 to first retract the shot pins 1098 and 1098' and then simultaneously open shoe 1070 and shoes 1144 and 1146. This opening motion of shoe 1144 trips the microswitch controlling cylinders 1030 and 1030' as well as cylinders 1048 and 1048' so that shelves 1020 and 1022 and fingers 1044 and 1044' are simultaneously retracted to their open positions shown in solid lines in FIG. 42. This motion, in turn, actuates a solenoid control valve controlling the air cylinder 1002 (FIG. 39) causing its plunger to drop to its lower limit of travel indicated in broken lines in FIG. 39. Since there is air pressure already acting on the piston in cylinder 994 urging plunger 992 downwardly, the lower end 998 of plunger 992 will track the

downward motion of the plunger 1000 until end 998 comes to rest against the end surface 1003 of cylinder 1002, as indicated by the lowermost position of head 998 shown in broken lines in FIG. 39. This second stage 5 of downward travel of plunger 992 propels pushers 946 and 948 downwardly through the distance indicated B in FIG. 38. As this movement is initiated, pusher flanges 952 and 952' will push the completed space-expander downwardly against and along the conical surface 932. This expands the spacer-expander to thereby open its parted ends so that they will strike the downwardly and outwardly diverging surfaces of another gap spreading guide 1072' (FIGS. 39 and 42) provided on the upper end of block 1072 to thereby 10 again spread the parted ends so they clear the support block 1072 as the spacer-expander is pushed downwardly along surface 928 and the corresponding surface of expander 936 by pushers 946 and 148.

When pushers 946 and 948 reach their lowermost 20 position, another microswitch (not shown) is actuated to actuate cylinder 994 to lift the pushers 946 and 948 back up through distances B and A until they reach their uppermost position shown in solid lines in FIG. 38. At the same time, cylinder 1002 is actuated to elevate its plunger 1000 to its uppermost position shown in solid lines in FIG. 39. When pushers 946 and 948 reach their uppermost position, cylinders 1012 and 1014 are actuated to extend their plungers toward one another to open the pushers 946 and 948 to their 25 spread-apart positions shown in FIGS. 37 and 41 wherein station No. 8 is conditioned to receive another spacer-expander on cone 910. The aforementioned 30 cycle is then repeated.

As successive spacer-expanders are pushed to the 35 lower limit of distance B indicated in FIG. 38, they stack up and push the preceding expanders downwardly on surface 934 of guide 926. When guide 926 is full of spacer-expanders from the lower limit of distance B down to the lower horizontal edge 927 of guide 40 926, the next spacer-expander to be pushed downwardly through distance B by pushers 946, 948 will cause the leading spacer-expander poised at edge 927 to be shoved downwardly off guide 926 onto a cylindrical loading tube 1200 of station No. 9.

STATION NO. 9

In station No. 9, the completely formed spacer-expanders 58 are loaded on a paper tube 1200 which is supported and operated by the structure of station 50 No. 9 as shown in FIGS. 1, 37, 39, 40 and 44. As best seen in FIGS. 1 and 37, an angle iron beam 1202 is secured to one of the legs 1204 of frame 102 of machine 100 and carries at its outer end three vertical posts 1204, 1206 and 1208 secured at their upper ends to a plate 1210 fixed to beam 1202 and at their lower ends to another plate 1212. A bushing block 1214 is slidably guided on posts 1206 and 1208 (FIG. 40) and has an arm 1216 secured to another collar 1218 which receives another post 1219 (FIGS. 37 and 40). Block 55 1214 is held in its uppermost position shown in FIG. 37 by a cam follower roller 1220 rotatably supported on block 1214 which rides on the upper edge 1222 of a barrel-type cam 1224. Cam 1224 is journaled on post 1204 and held against axial movement by a collar 1225 affixed to post 1204 above the hub of cam 1224. When cam 1224 is rotated counterclockwise by pulling an upright handle 1226 in this direction, follower 1220 will 60 65

ride off of the horizontal surface 1222 and onto the sloping surface 1228 of cam 1224 to thereby lower block 1214 to its lowermost position shown in dotted lines in FIG. 37.

Block 1214 carries an angle bracket 1230 on which an upright air cylinder 1232 is supported. The plunger 1234 of cylinder 1232 extends upwardly from its upper end and carries a circular table 1236 on which the lower end of the cylindrical paper tube 1200 is adapted to rest. Tube 1200 is centered on table 1236 by a chamfered plug 1238 secured to the upper surface of table 1236 and adapted to fit snugly within the lower end of the hollow tube 1200. A tension coil spring 1240 secured to a bracket 1242 extends around plug 1238 and is cammed outwardly when the lower end of tube 1200 is slipped downwardly onto plug 1238 to thereby assist in releasably retaining tube 1200 frictionally on table 1236.

In the raised position of table 1236 as shown in FIG. 37, the upper end of tube 1200 fits within the hollow interior of the lower end of guide 926 so that the upper edge 1244 of tube 1200 is disposed above the lower edge 926 (FIGS. 37, 39 and 44), but by a distance less than the vertical lift imparted by cam 1224.

Tube 1200 is vertically reciprocated a distance slightly greater than the axial dimension of a single spacer-expander 58 once during each cycle of station No. 8 to move the tube up through the stack of spacer-expander rings 58. The stack is held stationary during this tube movement by the uppermost ring of the stack engaging the lower edge 927 of guide 926. Hence as tube 1200 slides up through the stack during its upward movement, the stack of rings 58 is moved downwardly relative to the tube. Thus when tube 1200 is lowered again by air cylinder 1232 to the position shown in solid lines in FIG. 37, a space has been cleared on tube 1200 just below edge 927 to receive another spacer-expander. Air cylinder 1232 is operated by a solenoid valve synchronized with the operation of station No. 8 by the microswitch which is actuated when pushers 946 and 948 reach the lower limit of the travel distance A shown in FIG. 38. This insures that tube 1200 has been cycled through its short up and down motion prior to pushers 946 and 948 completing their downward travel through the distance B to thereby push the lowermost spacer-expander off of guide 926 onto the space made available on the upper end of tube 1200.

This tube loading sequence is repeated until tube 1200 is completely filled with a stack of rings 58, whereupon the machine attendant pulls handle 1226 to rotate cam 1224 counterclockwise to drop table 1236 to its lowered position shown in broken lines in FIG. 37. This lowers the upper end of tube 1200 clear of the lower end of guide 926 a sufficient distance so that the attendant can lift the loaded tube 1200 off plug 1238. The attendant then seats an empty tube 1200 on table 1236, and the tube is then reinserted in guide 926 by moving handle 1226 back to the position shown in FIG. 37.

The stack of rings 58 are retained on tube 1200 in the angular orientation imparted in transfer to and through station No. 8 by a vertical bar 1250 (FIGS. 37 and 39) which is secured to frame 920 and extends closely adjacent the periphery of tube 1200 and parallel to the axis thereof. The upper end of bar 1250 forms a continuation of plate 1072 and extends downwardly substantially to the lower end of tube 1200. Thus, when tube

1200 with a full load of spacer-expanders 58 thereon is removed from machine 100, they will be oriented with their parting gaps aligned for further processing, such as deburring, plating and finishing operations.

MALFUNCTION, SENSING AND CONTROL SYSTEM

Machine 100 preferably is equipped with a malfunction detection and shutdown system which utilizes the yieldably restrained covers of the strip guides 216, 218, 220 and 222 described previously to halt operation of machine 100 quickly in the event that a jame-up should occur in any one of the stations Nos. 1-5 inclusive.

Referring first to station No. 4 as illustrated in FIGS. 15 and 6, an electrically conductive metallic grounding finger 1260 is mounted on an arm 1262 secured to the underside of frame 104. Finger 1260 is cantilevered from the lower end of arm 1262 so as to extend horizontally with a clearance of about one-sixteenth to one-eighth inch over the uppermost position of the upper surface of the free end of presser blade 368, i.e., its normal position in the open condition of die assembly 142 of station No. 4. One lead of an electrical malfunction circuit (not shown) is connected to arm 1260 and the other lead is connected to presser blade 368, either directly or as a ground connection via the electrically conductive metal components of machine 100. The other ends of these two leads are connected to the input terminals of a suitable commercially available malfunction relay control. The output terminals of the control are connected to the actuating circuits for magnetic brakes 118 and the electrically actuated clutch 112, as well as to suitable alarm devices.

When machine 100 is operating normally and strip 170 is being fed smoothly and easily through the strip guideway of station No. 4, the malfunction input circuit will be open between contact 1260 and pusher 368, thereby allowing the magnetic brakes 118 to remain in their "off" condition and clutch 112 to remain engaged so that shaft 114 is rotated by motor 106 in its normal manner. However, should a malfunction occur in station No. 4, or in station No. 5, which in some way interferes with the passage of strip 170 through the guideways of stations Nos. 4 or 5, the continuous intermittent advance of strip 170 imparted by feeder 154 will cause the strip to bow, buckle and pile up. This will create sufficient upward force on guide 222 to overcome the yieldable restraint imparted by spring 380 and lift pressure blade 368 relative to stripper 246. When blade 368 has been lifted through the normal gap clearance between its upper edge and contact blade 1260, blade 368 will contact the undersurface of blade 1260 on the upstroke of stripper 246 as die assembly 142 is opened. This closes the input circuit to the malfunction control which responds by producing an output signal which actuates magnetic brakes 118 and clutch 112, thereby decoupling the drive to shaft 114 and causing brakes 118 to seize shaft 114 to bring the reciprocating motion of the rams 126, 128 and 130 rapidly to a halt.

In like manner, three additional fingers identical to finger 1260 are positioned respectively over guide 216, 218 and 220, these fingers not being shown since their construction and operation will be well understood from the foregoing description of finger 1260. These three additional fingers likewise are spaced slightly above the movable but yieldably restrained upper covers of guides 216, 218 and 222 respectively. Each cover

thus functions as the movable contact, and each finger as the stationary contact, of a normally open switch in an input circuit paralleled with the input circuit at the fourth station and connected to the input terminals of the malfunction relay control. Hence should a strip jam-up occur in station Nos. 1, 2 or 3, the associated cover of guides 216, 218 or 220 will respond by raising beyond its normal position into contact with its associated contact finger to thereby generate a malfunction signal operable to throw out clutch 112 and simultaneously actuate magnetic brakes 118 to stop machine 100.

The aforementioned malfunction system thus is operable to sense a jam-up of strip 170 regardless of where it occurs in its path of travel through stations Nos. 1-5 inclusive to thereby reduce or prevent the damage to the punches and dies of stations Nos. 1-5 inclusive which otherwise would result from their continued operation subsequent to a strip jam malfunction.

Scrap Removal System

It is to be understood that machine 100 has a vacuum system (not shown) connected to vertical passageways in the lower die shoes of stations Nos. 1, 2, 3 and 7 for vacuum removal of the scrap material punched from strip 170 at these stations. In addition, at station No. 8, block 1072 has a similar vertical passageway (not shown) connected to the vacuum system with an inlet below the end surface 1114 of shear clamp 1110 to receive the severed flash pieces 192a and 192b.

It is to be understood that the subject matter of the progressive blanking and bending means of stations Nos. 1-5 inclusive of machine 100 disclosed herein is claimed in a co-pending application of Roy E. Overway and Frank G. Warrick, entitled "Machine for Forming Piston Ring Spacer-Expanders From Strip Stock," filed on even date herewith and assigned to the assignee herein.

I claim:

1. Apparatus for forming strip stock into rings comprising a coiling die assembly, means for feeding strip stock of generally channel-shaped cross-section with a step-by-step movement through said coiling die assembly, said coiling die assembly being located in the path of travel of the strip downstream from said feeding means and having a punch movable toward and away from the channel-shaped strip and an anvil disposed adjacent the side of said strip opposite said punch, said punch having a forming surface adapted to impart a coiling curvature to the strip in angular increments circumferentially of the strip to thereby progressively coil the strip into a ring, said anvil having a forming surface complementary to said forming surface of said punch, said punch being mounted for pivotal movement about an axis parallel to the axis of a ring being formed by said coiling die assembly such that said punch forming surface is movable toward and away from said anvil forming surface with the strip disposed between said forming surfaces to curve successive increments of the strip to thereby form a generally circularly shaped ring, and drive means for pivotally moving said punch to opened and closed positions of said coiling die assembly in synchronism with said strip feeding means to thereby advance the strip stock when said coiling die assembly is open and to hold the strip stock stationary during closing movement of said coiling die assembly.

2. The combination as set forth in claim 1 wherein said punch is operable against the side of said strip which becomes the outer periphery of the ring.

3. The combination as set forth in claim 1 wherein said axis about which said punch is mounted for pivotal movement is upstream of said forming surface of said punch relative to the direction of strip feed.

4. The combination as set forth in claim 1 wherein said drive means comprises a ram reciprocable in the direction of the opening and closing movement of said coiling die assembly, and an articulated linkage mechanically coupling said drive means to said coiling die punch and operable in response to closing movement of said ram to move said punch in a direction generally opposite to the direction of said closing movement of said ram, and vice versa.

5. The combination as set forth in claim 4 wherein said linkage has a lost-motion connection between said punch and said ram operable to cause said ram to impart closing movement to said punch during travel of said ram only in the last portion of said ram's closing movement, means biasing said punch to its open position during all but said last portion of the closing travel and the corresponding successive initial opening travel of said ram, and wherein said strip feeding means is operable to feed said strip when said coiling punch is open.

6. The combination as set forth in claim 5 wherein said linkage comprises a rigid arm secured to said ram and extending to said coiling die assembly and having a follower dependent therefrom, a first lever pivoted for movement in a plane aligned with the path of travel of said arm follower, a rock shaft mounted for rotation about the longitudinal axis of said shaft and oriented with said axis perpendicular to said plane, a second lever secured to one end of said shaft and extending radially therefrom in converging relation with said first lever, said second lever having a follower tracking on the side of said first lever opposite said arm follower, said coiling punch being secured to said rock shaft and extending radially therefrom generally in the opposite direction from said second lever, said arm follower contacting said first lever between its pivot point and said second lever follower during said last portion of the closing movement of said ram to thereby swing said coiling punch in a closing stroke in a direction opposite to the direction of travel of said arm follower.

7. The combination as set forth in claim 1 further including a cut-off punch and die assembly positioned between said feeding means and said coiling die assembly, said cut-off punch and die assembly having a punch reciprocable across the path of travel of said strip to sever the uncoiled portion of the strip from the leading coiled portion of the strip, and means for operating said cut-off punch member through its working stroke at regular intervals corresponding to a given number of coiling punch strokes.

8. The combination as set forth in claim 7 wherein said cut-off punch and die assembly comprises a stationary cut-off die having an end surface facing said cut-off punch and extending in the direction of strip feed from upstream of said cut-off punch to at least the entrance ends of said coiling punch and anvil, and a guideway for feeding said channel-shaped strip onto said end surface of said cut-off die with said strip oriented with its median portion sliding along said end sur-

face and its side margins bearing against said anvil forming surface.

9. The combination as set forth in claim 8 wherein said cut-off die has a narrow trailing rib disposed opposite said coiling anvil and aligned with the strip median, and wherein said coiling punch has a slot in its entrance end receiving said rib therein, said rib having an end surface forming an extension of said cut-off die end surface and being generally flush with said coiling punch surface in the closed position thereof.

10. The combination as set forth in claim 7 wherein said cut-off punch operating means comprises a movable linkage coupled between said ram and coiling die assembly drive means, said linkage having a part movable in a direction of motion parallel to that of the working stroke of said cut-off punch, and a shuttle part carried on said linkage part for movement therewith, said shuttle part also being movable in a direction perpendicular to said travel of said cut-off punch between positions engaging and clearing said cut-off punch to thereby respectively connect and disconnect said linkage in driving relation with said cut-off punch, and means for moving said shuttle part to its engaging position at said regular intervals to transfer one stroke of said ram to said cut-off punch.

11. The combination as set forth in claim 10 wherein said anvil is disposed above said strip and said coiling punch is disposed below said strip, said forming surfaces of said coiling punch and anvil curving upwardly whereby said strip is coiled upwardly by striking the outer periphery thereof to position the fully coiled ring above said coiling punch.

12. The combination as set forth in claim 6 further comprising a cutoff punch and die assembly positioned between said feeding means and said coiling die assembly, said cut-off punch and die assembly having a punch reciprocable across the path of travel of said strip to sever the uncoiled portion of the strip from the leading portion of the strip, a movable linkage coupled between said ram and said drive means of said coiling die assembly, a part mounted on said rigid arm of said linkage and movable in a direction of motion generally parallel to that of the working stroke of said cut-off punch, and a shuttle part carried on said part mounted on said rigid arm for movement therewith, said shuttle part also being movable in a direction generally perpendicular to said travel of said cut-off punch between positions engaging and clearing said cut-off punch to thereby respectively connect and disconnect said linkage in driving relation with said cut-off punch, and means for moving said shuttle part to its engaging position at regular intervals to transfer one stroke of said ram to said cut-off punch.

13. The combination as set forth in claim 7 wherein said coiling die assembly has a guide plate mounted adjacent the path of travel of said strip as it curls up into a coil upon leaving said coiling punch and anvil, and means for directing an air blast adjacent said guide plate directed toward said coiled strip in response to said strip being severed by said cut-off punch to thereby eject the severed coiled ring endwise in a direction transverse to strip feed.

14. The combination as set forth in claim 13 wherein said air blast means comprises a semi-circular tube positioned adjacent but radially outwardly of the position of a fully coiled ring and adjacent said plate, said tube having nozzle means circumferentially spaced along

the inner periphery of said tube for directing a plurality of air jets radially inwardly toward said ring and generally parallel to said plate.

15. The combination as set forth in claim 13 wherein said guide plate has an entrance portion adjacent the exit ends of said coiling punch and anvil and inclined from the plane of said guide and diverging outwardly from the path of travel of said strip to feed the severed leading end of the strip onto the guiding surface of said plate.

16. The combination as set forth in claim 13 further including a stringer tube adapted to receive said severed ring thereon, said tube having an entrance nose positioned generally within the area bounded by said ring when said ring is positioned adjacent said plate in its substantially completely coiled form.

17. The combination as set forth in claim 16 wherein said stringer tube has a cylindrical portion smaller in diameter than that of the completely coiled ring but sufficiently large to prevent the gaps of said ring from passing transversely thereover, and said tube has a ring orienting fin extending radially outwardly from said tube and running lengthwise thereof, said fin being generally aligned with said cut-off punch and die assembly so that the parted ends of said ring as it is being severed from said strip are disposed on opposite sides of said fin.

18. The combination as set forth in claim 17 wherein said guide plate has an apron inclined downwardly and outwardly therefrom disposed over the path of travel of said strip leading onto said cut-off die assembly, said apron being positioned to slidably divert the leading end of the coiled strip outwardly toward said stringer tube preparatory to severance of said coiled strip and transfer of the severed ring to said stringer tube.

19. The combination as set forth in claim 18 wherein said fin has a flange extending transversely from the longitudinal edge of said fin remote from said stringer tube, said apron extending at its trailing end adjacent to said fin and above said flange.

20. The combination as set forth in claim 6 further including a forming die assembly located in the path of strip feed between said feeding means and said coiling die assembly, said feeding means feeding said strip stock in generally flat form with a step-by-step movement through said forming die assembly, said forming die assembly being adapted to form successive increments of said strip into a generally channel-shaped cross-section, said ram having a direct one-to-one connection to said forming die assembly and being reciprocable upwardly and downwardly to impart opening and closing movement respectively to said forming die assembly and coiling die assembly to operate said forming and coiling die assemblies in synchronism but in opposite directions.

21. Apparatus for forming strip stock into rings comprising a coiling die assembly, means for feeding strip stock of generally channel-shaped cross-section with a step-by-step movement through said coiling die assembly, said coiling die assembly being adapted to curve successive increments of said strip to thereby form a generally circularly shaped ring, said coiling die assembly being located in the path of travel of the strip downstream from said feeding means and having a punch movable toward and away from the channel-shaped strip, said punch having a forming surface adapted to impart a coiling curvature to the strip in angular incre-

ments circumferentially of the strip to thereby progressively coil the strip into a ring, said coiling die assembly also having a stationary anvil disposed adjacent the side of said strip opposite said punch and having a forming surface complementary to said forming surface of said punch, drive means for opening and closing said punch in synchronism with said strip feeding means to thereby advance said strip when said coiling die assembly is open and to hold said strip stationary during closing movement of said coiling die assembly, a cut-off punch and die assembly positioned between said feeding means and said coiling die assembly, said cut-off punch and die assembly having a punch reciprocable across the path of travel of said strip to sever the uncoiled portion of the strip from the leading coiled portion of the strip and a stationary cut-off die having an end surface facing said cut-off punch and extending in the direction of strip feed from upstream of said cut-off punch to at least the entrance ends of said coiling punch and anvil, means for operating said cut-off punch through its working stroke at regular intervals corresponding to a given number of coiling punch strokes, and a guideway for feeding said channel-shaped strip onto said end surface of said cut-off die with said strip oriented with its medium portion sliding along said end surface and its side margins bearing against said anvil forming surface.

22. The combination as set forth in claim 21 wherein said cut-off die has a narrow trailing rib disposed opposite said coiling anvil and aligned with the strip median, and wherein said coiling punch has a slot in its entrance end receiving said rib therein, said rib having an end surface forming an extension of said cut-off die end surface and being generally flush with said coiling punch surface in the closing position thereof.

23. The combination as set forth in claim 21 wherein said cut-off punch operating means comprises a movable linkage coupled between said ram and coiling die assembly drive means, said linkage having a part movable in a direction of motion parallel to that of the working stroke of said cut-off punch, and a shuttle part carried on said linkage part for movement therewith, said shuttle part also being movable in a direction perpendicular to said travel of said cut-off punch between positions engaging and clearing said cut-off punch to thereby respectively connect and disconnect said linkage in driving relation with said cut-off punch, and means for moving said shuttle part to its engaging position at said regular intervals to transfer one stroke of said ram to said cut-off punch.

24. The combination as set forth in claim 23 wherein said anvil is disposed above said strip and said coiling punch is disposed below said strip, said forming sur-

faces of said coiling punch and anvil curving upwardly whereby said strip is coiled upwardly by striking the outer periphery thereof to position the fully coiled ring above said coiling punch.

- 5 25. Apparatus for forming rings from strip stock having a sufficient continuous axial length to permit multiple rings to be formed therefrom comprising a coiling die assembly, means for feeding strip stock with a step-by-step movement through said coiling die assembly, 10 said coiling die assembly being located in the path of travel of the strip downstream from said feeding means and having a punch movable toward and away from the strip stock and a stationary anvil having a curved forming surface disposed adjacent the side of the strip stock 15 opposite said punch for imparting a coiling curvature to a segment of the strip stock in angular increments circumferentially of the strip stock to thereby progressively coil a portion of the strip stock into a ring, a guide for aligning and retaining an axially extending portion of the strip stock upstream of said punch generally tangential to a point on the curved forming surface of said anvil, said punch having a forming surface complementary with said curved forming surface of said anvil, said punch forming surface extending only generally downstream of said point such that said die assembly 20 imparts a coiling curvature to the strip stock only generally downstream of said point, said guide bearing on a side of the strip stock remote from the anvil and upstream of said point to thereby retain said axially extending portion of the strip stock upstream of said punch generally tangential to said point while said coiling die assembly imparts a coiling curvature to a portion of the strip stock downstream of said point, and drive means for moving said punch to opened and 25 closed positions of said coiling die assembly in synchronism with said strip feeding means to thereby advance the strip stock when said coiling die assembly is open and to hold the strip stock stationary during closing movement of said coiling die assembly.

- 30 40 26. The combination as set forth in claim 25 wherein said forming surface of said punch is mounted for pivotal movement about an axis upstream of said forming surface of said punch relative to the direction of strip feed and parallel to the axis of a ring being formed by said coiling die assembly.

- 35 45 27. The combination as set forth in claim 26 wherein said anvil is disposed above said strip and said punch is disposed below said strip with said forming surfaces of said punch and anvil curving upwardly whereby said strip is coiled upwardly by said coiling die assembly to position the fully coiled ring above said punch.
